TRAFFIC ACTUATED CONTROL APPARATUS
Charles L. Du Vivier, Darien, Conn., assignor, by mesne assignments, to Laboratory for Electronics, Inc., Boston, Mass., a corporation of Delaware
Filed May 9, 1960, Ser. No. 27,605
9 Claims. (Cl. 340—36)

This invention relates to traffic actuated control apparatus or systems, and more particularly to apparatus for automatic reversal of the right-of-way of directional flow of traffic over one or more lanes of a multi-lane street, roadway or the like, in response to traffic conditions as obtained by a sampling of such traffic conditions by traffic actuation.

From one aspect the invention relates to improved apparatus for the selection of an off-center traffic flow between two directions along the same roadway in response to traffic actuation by traffic flowing in the respective directions along such roadway, as for example, inbound and outbound traffic.

From another aspect the invention relates to an improved control system for varying the number of lanes for opposite directions of traffic along a multi-lane roadway, allocation of a reversible lane or lanes being made to the direction of traffic flow having the heavier or predominating traffic as determined by sampling of the respective traffic flows in opposite directions along the controlled roadway. The reversible lane or lanes may also be placed on a neutral basis without assignment to either one direction in response to substantially balanced traffic in opposite directions along the road or in case there is no substantial predominance of traffic in one direction over the other.

DISCUSSION OF PRIOR ART

The off-center or unbalanced allocation of road width for bi-directional traffic along a multi-lane street or roadway, as by two lanes in one direction and one lane in the opposite direction, for example, has been employed previously to expedite rapid movement of unbalanced traffic, i.e. traffic substantially heavier in one direction than in the other direction on the same street or roadway.

It is well known in the field of traffic control to reverse as desired, the direction of traffic flow, along center lanes of a multi-lane roadway serving bi-directional traffic, thereby alternating the off-center traffic movement between the two traffic flows, as desired. It is also already known to have the center lane neutral or not allocated exclusively to either direction for periods of substantially balanced traffic.

A paper entitled "Reversing Flow in Center Lane of 3-Lane Roads" by Melville M. Todd, appearing on pages 29 to 37 of the "1949 Proceedings" of the Institute of Traffic Engineers at New Haven, Connecticut, copyright 1949, is one of several articles published on the subject of control of a reversible lane of a multi-lane roadway.

An article, "Unbalanced Traffic Flow on Three or Four Lane Streets," by Joseph F. Rice appearing on pages 137 to 153 of "Traffic Quarterly" of January 1956 published by the Eno Foundation for Highway Traffic Control, Inc. at Saugatuck, Connecticut, copyright 1956, also discusses the subject of control of reversible lanes of a multi-lane bi-directional roadway. At the end of Joseph F. Rice's said article is a bibliography in which are listed other articles on the same subject.

A paper entitled "A Traffic Actuated Cycle and Offset Selector System" by John L. Barker, development engineer for Automatic Signal Division of Eastern Industries, Incorporated, Laboratory for Electronics, Inc., the assignee of the present invention, appears on pages 70

2

to 76 of the aforementioned "1949 Proceedings" and mentions Mr. M. M. Todd's paper.

Mr. Barker's paper relates to several aspects of signal systems providing for non-preferential treatment or preferential treatment for traffic flow in opposite directions along a road, for example, in response to relative traffic demand in such directions. Mr. Barker's U.S. Patent 2,542,978 issued February 27, 1951, for "Traffic Actuated Control Apparatus," and assigned to the assignee of the present application, presents some examples of systems and apparatus relating to non-preferential and preferential directional control of traffic flow in respect to comparative actuation in the respective directions as more fully set forth in said patent.

15 The interrelated French Patents 992,198 and 992,202, delivered July 4, 1951, both are examples of prior art relating to allocation of a reversible central traffic lane of a roadway to one or the other direction or to a neutral condition in response to traffic actuation to vary the number of lanes allocated to the respective opposite directions in accordance with relative traffic demand in the respective directions.

SEVERAL ASPECTS OF THE PRESENT INVENTION

25 From one aspect the present invention is a greatly improved lane changing or reversing system and apparatus, including vehicle detection devices for detecting vehicle traffic of the respective flows of traffic in opposite directions on a roadway, traffic measuring devices for the respective flows of traffic, a comparison device or controller that determines the relation between the measurement of the two directional traffic flows as presented by the traffic measuring devices, one or more 30 master lane changers, responsive to the controller, and one or more local lane changers associated with and responsive to each master lane changer for control of the direction of traffic flow through selective signal indications, in one or more traffic lanes jointly or individually, of a multi-lane roadway.

35 Within the present greatly improved lane changing system and apparatus is the inclusion of certain novel components as part of the traffic measuring devices. By employing multiple vehicle detectors in the respective traffic measuring devices, with the vehicle detectors individual to each lane as well as individual to each direction of potential traffic flow in the lane, certain of the vehicle detectors are automatically selected and connected to an associated counting or measuring unit according to the direction of traffic permitted in the lane 40 in which the vehicle detector is located.

45 Alternate selection apparatus for vehicle detection, including vehicle detectors individual to each lane but common to each direction of potential traffic flow in the lane, and the channeling of the detection impulse to a selected counting or measuring unit in response to the master lane changer and according to the direction of traffic permitted in the lane in which the vehicle detector is located, is also offered as another means by 50 which an accurate representation of vehicle traffic on the roadway may be obtained.

55 Still another alternate selection apparatus including vehicle detectors individual to each lane and common to each potential direction of traffic flow in the individual lane, provides for the automatic directing or channeling of the vehicle detection impulse to a counting or measuring device according to the direction of travel of the vehicle so actuating the vehicle detector.

60 From another aspect the present invention provides a novel lane changing system for control of the directional flow of traffic in two or more traffic lanes of a multi-lane roadway in which each of two or more traffic

lanes is individually controlled by a master lane changer thus providing one master lane changer for each lane of the two or more traffic lanes with each of the master lane changers partly controlled by the other master lane changer and partly controlled in common by one comparison device or master controller to allocate certain of such lanes to selected directions during normal or substantially balanced traffic conditions as well as during certain unbalanced traffic conditions so as to provide positive allocation of directional use of the controlled traffic lanes at all times except during transition from one directional allocation to another directional allocation.

With the present novel system employed for individual control of directional allocation of each lane of two adjacent traffic lanes located between additional traffic lanes, use of the two adjacent traffic lanes may be allocated to opposite directions of traffic flow respectively during normal or substantially balanced traffic with use of both lanes allocated to the same directional traffic flow during peak traffic conditions. Such system and apparatus may include partial control of one master lane changer by the other master lane changer so as to insure that the desired cycle of allocation of the reversible lane is obtained.

OBJECTS OF INVENTION

It is an object of the present invention to present an improved system or apparatus for the control of the direction of traffic flow in a lane or lanes by reversing the direction of traffic flow in certain of the lanes of a multi-lane roadway or the like automatically, through traffic actuation, by the traffic traversing the controlled roadway, received from a sampling point or points along the roadway over a timed period, with means for allocating use of the certain lane or lanes to one directional traffic flow during at least a minimum period while prohibiting the opposite directional traffic flow from the certain lane or lanes, followed by a timed clearance period during which the traffic flow having last been allocated use of the certain lane or lanes is cleared or warned to leave such lane or lanes while still prohibiting the opposite traffic flow from the controlled lane, and thereafter prohibiting both traffic flows from the certain lane or lanes or providing a cautionary indication therein for at least a minimum period before permitting allocation of the certain lane or lanes exclusively by either traffic flow.

Another object is to present an improved actuated system and apparatus for the control of the directional flow of traffic on certain of the lanes of a multi-lane roadway that has such degree of flexibility that a certain directional phase of traffic flow may, after having terminated, be repeated before providing the opposite directional phase of traffic flow, according to the demand of the traffic along the controlled roadway.

A further object is to present an improved actuated controlled system for controlling the direction of traffic flow along a lane or lanes of a multi-lane roadway serving bi-directional traffic having at least a minimum period prohibiting vehicles in the lane or lanes following a clearance period of such lane or lanes between two directional periods.

A still further object is to provide an improved system and apparatus for controlling the direction of traffic flow along a lane or lanes of a multi-lane roadway serving bi-directional traffic and having a control cycle including one part of the cycle for directional allocation of the lane or lanes which one part of the cycle is common to both directional allocations alternatively, as presented for one direction or the other.

Another object is to provide a novel system and apparatus for the control of directional traffic in at least two adjacent interior traffic lanes of a multi-lane roadway by individually controlling the direction of traffic

flow in each individual lane of the two adjacent interior traffic lanes by the use of lane changers individual to each lane, with the lane changers interconnected so as to provide partial control of each lane changer by the other with both lane changers controlled in common by a comparison unit or master controller.

It is still another object to provide an improved lane changing system in which positive allocation of a lane or lanes of a multi-lane roadway serving bi-directional traffic may be made at all times except during transition from one allocation of direction to another allocation of direction.

A still further object is to provide an improved lane changing or reversing system in which two or more lane changers are employed to control a similar number of lanes of a multi-lane roadway with the lane changers individually favoring one direction of traffic flow so that during peak traffic both lane changers will allocate their respective lane to the same direction of traffic flow and during average or non-peak traffic periods each lane changer will allocate its respective lane or lanes to the opposite directional traffic flow from the other.

Traffic measuring and comparison aspects of reversible lane system

It is already known to provide apparatus for selection, by traffic actuation at a suitable traffic sampling point, between different types or lengths of traffic control cycles for a traffic signal system or to adjust the time of the overall traffic signal system step-by-step at short time intervals to accommodate the actual traffic variations as they occur. Such apparatus may be employed in the present system to select a step in a scale of steps which step is proportional to the volume of traffic actuating such apparatus.

Apparatus of this character is sometimes referred to as a cycle selector and is disclosed in U.S. Patent Number 2,288,601, issued July 7, 1942, to John L. Barker.

In the preferred embodiment of the present invention, allocation of use of a lane or lanes of a multi-lane roadway, to one directional flow of traffic is made in accordance with the relative position of selected steps of two comparable scales, each scale being divided into comparable steps with one of the steps of each scale selected by a cycle selector in response to vehicle actuation of traffic in one directional flow. One scale may represent inbound traffic, for example, and the other scale may represent outbound traffic, for example and the individual steps of the scale may represent progressive measurements of the traffic flow or traffic volume, for example. The relation between the selected steps of two comparable scales may be determined by a system selector which may be in the form disclosed in the aforesaid U.S. Patent 2,542,978, issued February 27, 1951, to John L. Barker.

Accordingly one cycle selector and its associated vehicle detector units are provided to detect and measure inbound vehicle traffic at an appropriate sampling point on a multi-lane roadway serving bi-directional traffic of which one or more traffic lanes are to be used as reversible lane or lanes to accommodate the predominately heavy traffic flow while another cycle selector and its associated vehicle detector units are provided to detect and measure outbound vehicle traffic at an appropriate sampling point on the same roadway. The terms inbound and outbound are representative and used merely for convenience of identifying opposite directions of traffic flows.

The steps of the scale or cycle positions selected by each cycle selector may correspond to the volume or measurement of traffic detected in each respective direction on the roadway and selection is made in the form of energizing an output line selected among several output lines. The several output lines of the steps of the respective scales are applied to a system selector which may be referred to as a master controller and the master con-

troller determines the relation between the energized steps of the respective scales and accordingly sets up a demand for certain traffic conditions. Response to such demand is made by a master lane changer which may proceed through a cycle of operations and provide outputs for control of one or more local lane changes or signal control circuits which provide the desired signal indications over the traffic lane or lanes of the controlled roadway.

The position and number of sampling points along a roadway are a matter to be determined by the length of the controlled reversible lane or lanes and the character and pattern of the traffic. It may be desired to have multiple sampling points for each directional traffic flow along a controlled highway that is relatively long so that the differential between two directional flows of traffic along the roadway will more faithfully represent the differential between the two directional flows along the entire roadway rather than at the sampling point only.

If the controlled roadway is relatively short and is a roadway with numerous access roads along its length it may be desired to have sampling points for each traffic flow more or less centrally located along the length of the roadway.

If, on the other hand, the controlled roadway is relatively short and/or is without access roads along its length, for example, a tunnel or bridge, effective sampling points may be placed at each end of the tunnel or bridge to sample the approaching traffic or entering traffic from each direction.

Reversible lane control systems of FIG. 1 and FIG. 6 and in general

For purposes of illustration of the invention relative to FIGS. 1 and 6 it will be assumed that the controlled roadway is a three lane road accommodating two way traffic, for example, inbound and outbound. The northbound lane, for example, may be for traffic inbound to a business area of a city and the southbound traffic lane, for example, may be for traffic outbound away from the business area. During normal traffic conditions, one lane, L1, the easterly lane of the roadway will be used by inbound traffic, and one lane, L3, the westerly lane of the roadway will be used for outbound traffic. The center lane, L2, during normal traffic conditions will be used as a buffer lane or safety zone between the inbound and outbound traffic.

In the field of traffic control it is known that at various times large increases of traffic flow in one direction occurs, as for example in the morning, people may travel into the city to their place of employment, and in the afternoon, people may travel from the city to their homes.

This increase in traffic flow in one direction is generally referred to as peak traffic and peak traffic periods will occur at different times of day according to the season, weather, public events that attract numerous people and according to the days of the week, for example, weekdays and weekends.

The invention as embodied in block form in FIG. 1 and FIG. 6 automatically provides exclusive use of additional travel space or traffic lanes for peak traffic as determined from a relation between measurements of the two traffic flows of the traffic itself. During non-peak traffic periods or balanced traffic periods such additional traffic space or lane is employed either as a buffer zone between two traffic flows or as a lane used by both traffic flows for "passing only," when safe.

It will be assumed that the center lane of a roadway will be controlled so that during periods of peak traffic flow use of the center lane will be permitted by such peak traffic flow. Thus, during peak inbound traffic periods (inbound to a city, for example) the inbound traffic will be permitted to occupy the center lane as well as the easterly lane L1 which is here considered the normal lane for inbound traffic, while outbound traffic is restricted to the westerly lane, L3 its normal lane. Dur-

ing peak outbound traffic periods (outbound from a city, for example) the outbound traffic will be permitted to occupy the center lane as well as the westerly lane L3 while inbound traffic is restricted to the easterly lane L1.

- 5 During non-peak or normal, or average traffic flow periods the center lane will be employed as a safety or buffer zone between the two traffic flows.

According to one form of the invention, the traffic actuated detector units, of which there would be two accorded to inbound traffic and two accorded to outbound traffic, would be so placed that one detector would be actuated by inbound traffic in the easterly lane L1 and one detector would be actuated by outbound traffic in the westerly lane L3. The two remaining detector units, one for inbound traffic and the other for outbound traffic, would be placed so as to be actuated by traffic using the center lane L2 of the roadway. One such detector would be associated with, and in close proximity to the inbound traffic detector in the easterly lane and the remaining, or fourth detector would be associated with and in close proximity to the outbound traffic detector in the westerly lane of the roadway.

The detector units may be of any of the well known type of detectors in general use for vehicle traffic actuation. They may be either pressure operated, magnetic or sound sensitive, electrical or electronic, or may be of the radar type. These detectors may be directional or non-directional under different circumstances as pointed out more fully below.

30 In some cases, as will be later explained, one such detector unit, of the two detector units placed in the center lane, may be omitted so that three detector units may be used instead of four. In the case of multiple sampling points a number of detector units in excess of three or four, as the case may be, would be used depending upon the number of sampling points along the roadway. If three detector units were to be used at one sampling point, as will be later explained more completely, a single detector in the center lane would serve 35 both inbound and outbound traffic. The detector unit, being common to each directional traffic flow, may be a bi-directional detector in one case or a non-directional detector in another case as fully explained herein below.

In the operation of the cycle selector apparatus from 45 its broader aspects, the inbound and the outbound streams of traffic are respectively measured or counted over a period of time and during such time period the individual cycle selectors remain in a given cycle position of a scale of such positions corresponding to a scale of traffic 50 volumes previously measured.

Near the end of such traffic sampling time period, the individual cycle selectors determine whether to remain on the cycle position or to change to another and different position, in accordance with the traffic count, for example. If the traffic counted in one direction is substantially the same as in the preceding sampling time period the cycle selector associated with that direction remains on the same cycle position but if that traffic flow has increased substantially, the cycle selection associated 55 with that traffic flow will select the next higher cycle in the series unless the cycle selector is then selecting the highest cycle in such case it will remain on the highest cycle, or if the traffic count in one direction has decreased substantially, the cycle selector associated with that direction of traffic flow will select the next lower cycle in 60 the series unless the cycle selector is then on the lowest cycle position and then it will remain on the lowest cycle position.

At the end of each sampling time period, the counting 65 of traffic is reset and another sampling period is started. Each cycle selector has a number of different steps or cycle positions from which to select. U.S. Patent No. 2,288,601, referred to, illustrates six steps or cycle positions, from A to F, for example, although it is obvious 70 that more or less could be provided if desired. The

operation and complete description of the cycle selector is disclosed in the said Patent 2,288,601.

The operation of the system selector provides a means of setting up a demand in the lane changing system that will control allocation of use of the center lane of a roadway between the inbound traffic flow and the outbound traffic flow in accordance with the relative positions of the inbound and outbound cycle selectors. If, for example, the inbound and outbound cycle selectors are both on the same or corresponding steps or cycle positions, or not more than one cycle position apart, the system selector in accordance with one aspect of operation, will set up a demand in the lane changing system for a signal sequence which would deny use of the center lane to both inbound and outbound traffic and maintain the center lane of the roadway as a buffer lane or safety zone between the two directional traffic flows.

When the inbound and outbound cycle selectors are two or more cycle positions apart indicating a substantial difference in traffic volume or measurement in the respective directions, the system selector will select the highest cycle position and set up a demand to allocate use of the center lane to the traffic flow associated with the cycle selector then selecting the higher cycle position, thus according two lanes to one directional traffic flow as against one lane for the use of the other directional traffic flow.

When during a subsequent sampling time period the inbound and outbound cycle selectors return to corresponding cycle positions or are not more than one cycle position apart, the system selector will set up a demand in the lane changing system for a signal sequence that will convey instructions to traffic in the center lane to vacate the center lane to the right and will then prohibit use of the center lane to all vehicles and thereby maintain the center lane as a buffer lane or safety zone between the inbound and outbound traffic flow.

The signals used to control traffic in the center lane may be the conventional green for go, or use yellow for caution, or vacate or clearance, and red for stop or do not use. The use of arrows in the conventional color or signs conveying instructions may be desired to indicate non-use and to instruct the vehicle operators to vacate the lane by driving to the right.

Generally, the location of the signals controlling the use of the center lane may be overhead, in the center of the lane and placed between intersections, so as to eliminate possible confusion with the signals controlling intersection traffic. However, signals at intersections might supplement or coordinate in the lane allocation. The signals may very well be in a series of two sets of three signals back to back so to speak, one set of green, yellow and red signals that would be visible to and controlling inbound traffic and the second set visible to and controlling outbound traffic. The signals may be a set of double faced signals, that is, one unit containing three signals on each of two opposite faces and visible to and controlling the respective opposite directional traffic flows, the signals themselves being individually controlled.

It is preferred that the distance between signals controlling the directional traffic flow may be such that the inbound motorist, for example, can look ahead and see at least two sets of signals that control the inbound traffic flow and the outbound motorist, for example, can look ahead and see at least two sets of signals, at one time, that control the outbound traffic flow.

SUMMARY OF DRAWINGS

FIG. 1 illustrates, in block diagram form, a traffic actuated lane changing system employing apparatus according to one embodiment of the invention.

FIG. 2 illustrates, in circuit diagram form, a preferred form of the master lane changer with a cam chart associated with the cam contacts illustrated in the diagram, at the bottom of the figure.

FIG. 3 illustrates, in circuit diagram form, a preferred embodiment of the local lane controller usable in the systems of FIGS. 1 and 9 for example.

FIG. 4 illustrates, in circuit diagram form, a preferred form of the detector selector utilizing two single detector units for detection of traffic in the center lane, for use in FIG. 1 for example.

FIG. 5 illustrates, in circuit diagram form, an alternate form of detector selector utilizing a single detector unit for detection of traffic in the center lane for use in the several systems.

FIG. 6 illustrates in block form an alternate traffic actuated lane changing system employing apparatus differing somewhat from the apparatus employed in FIG. 1.

FIG. 7 illustrates a circuit arrangement combining the master lane changer, shown in FIG. 2 with the local lane changer shown in FIG. 3.

FIG. 8 illustrates, in circuit diagram form, the self-selecting detector selector employing a single bidirectional detector unit for traffic detection in the center lane for use in FIG. 1 or FIG. 6, for example.

FIG. 9 represents in block diagram form another alternate form of traffic actuated lane changing system employing apparatus for individual control of two reversible lanes.

FIG. 10 illustrates, in circuit diagram form an alternate form of lane changing unit or master lane changer.

General aspects of reversible lane system of FIG. 1

Referring now to FIG. 1 in more detail a section of roadway RY of a three lane road, formed by two solid lines, is illustrated extending from left to right along the upper part of the figure. The two broken lines, within the two solid lines, separate the roadway into three lanes, L1, L2 and L3. This roadway section illustrated may be part of a street, highway, or thoroughfare, for example, through which extends a controlled reversible center lane.

On the roadway, in sets of two, are four traffic actuated detector units, ID and IDD, that would detect inbound traffic and OD and ODD that would detect outbound traffic. These detector units may be of any well-known type adapted to close a pair of contacts upon passage of a vehicle, for example.

The detector unit ID, in the inbound lane L1, actuated by inbound traffic, is linked electrically to the cycle selector ICS which cycle selector will measure or count the inbound vehicle traffic in lane L1 during the sampling time periods. The detector OD, in outbound lane, L3, actuated by outbound traffic, is linked electrically to the cycle selector OCS, which cycle selector will measure or count the outbound vehicle traffic in lane L3 during the sampling time periods.

The detector unit IDD, in center lane L2 is associated with detector unit ID and is connected to the detector selector DS. During those periods that the inbound traffic is granted use of center lane, L2, detector selector DS, as will be fully explained hereinafter, links detector unit IDD electrically to cycle selector ICS through line IDL. The detector unit ODD in center lane L2 is associated with detector unit OD and is also connected to detector selector DS. During those periods that the outbound traffic is granted use of center lane, L2, detector selector DS links the detector unit ODD electrically to cycle selector OCS through line ODL.

Detector selector DS is connected electrically to the master lane changer MLC through lines GI and GO. Cycle selector, ICS, associated with inbound traffic, is connected to system selector MC by six lines AI, BI, CI, DI, EI and FI, which represent a separate circuit connection for each of the six cycle positions of cycle selector ICS. Likewise cycle selector, OCS, associated with outbound traffic, is connected to system selector MC by six lines AO, BO, CO, DO, EO and FO, which are

separate connections for each of the six cycle positions of cycle selector OCS.

System selector MC is connected to master lane changer MLC by two lines IG and OG, the use of which will be explained in detail hereinafter. Master lane changer MLC and local lane changer LLC are connected electrically by three lines, MIG, MOG and MCL. It is to be understood that one local lane changer is shown here for convenience of explanation, however, there could be multiple local lane changers spaced, as desired, along the controlled highway. The local lane changers would be connected in parallel to the master lane changer via the three lines MIG, MOG, and MCL with a common return through a ground line.

Local lane changer LLC is connected to the signals that control traffic on the controlled highway. The signals IGS, IYS, and IRS, green, yellow and red respectively, for inbound traffic control and OGS, OYS, and ORS, green, yellow and red respectively, for outbound traffic control are shown as two sets of three signals each for convenience. It is to be understood that the signals may be of any variety of colored light signals or mechanical device such as a movable arm or a semaphore type signal, for example. The light signals may be in the form of arrows or flashing signal lights or signs with lettered instructions.

Master lane changer of FIG. 2 and relation to FIG. 1

FIG. 2 herein illustrates a circuit diagram of the master lane changer, shown in the block diagram of FIG. 1 as a rectangle lettered MLC. The circuit of the master lane changer appears in FIG. 2 with a cam chart below the circuit diagram.

The circuit is arranged for 120-volt alternating current with the positive or ungrounded power terminal indicated by a plus in a circle in the upper left and the negative or grounded power terminal indicated by a minus in a circle in the upper right. The negative power line on the right marked 10, will be considered to be a common ground line. Lines IG and OG are input lines from the system selector shown in FIG. 1 as a rectangle lettered MC. Line IG continued through switch 210 and junction 211, is the input line for relay IR and line OG continued through switch 200 and junction 201 is the input line for relay OR. Relay IR is connected to ground line 10 by lines 11 and 10', and relay OR is connected to ground line 10 by lines 12 and 10'. Relay IL is connected to the A.C. input line 15 through a series of contacts that are controlled by relays IR, OR, CL and G as will be hereinafter described in detail. Relay IL is connected to ground line 10 by lines 16 and 10'. Relay OL is connected to the A.C. input line 15 through several contacts that are controlled by relay IR, OR, CL and G, as will be described in detail hereinafter. Relay OL is connected to ground line 10 by lines 17 and 10'.

Relay CL is connected to A.C. input line 15 through line 18, cam contacts C1-C2, when closed, and line 19. The circuit is completed to ground line 10 through lines 20 and 10'. Relay G is connected to the A.C. input line 15 through line 18, cam contacts D1-D2, when closed, and line 21. The circuit for relay G is completed to ground line 10 through lines 22 and 10'.

Relays IGR and OGR are connected to the A.C. input line 15 through a series of contacts controlled by relays IL, OL and G, as will be explained hereinafter. Relay OGR is connected to ground line 10 by lines 23 and 24 and relay IGR is connected to ground line 10 by line 24.

A motor ST, used for timing purposes, controls the cam contacts A1-A2, A2-A3, B1-B2, B2-B3, C1-C2, D1-D2, E1-E2 and E2-E3 which cam contacts are opened and closed in a predetermined sequence as will be hereinafter explained. It should be noted that this type of timing unit is shown here for purposes of convenience only, as other timing methods familiar to those skilled in the art, could be used with equal efficiency and

results, as for example a familiar telephone rotary stepping switch or line switch rotated by a motor magnet controlled by a timing device.

The motor ST is connected to the A.C. input line 15 through a series of contacts that are controlled by relays OR, OL, IR, and IL, and the cam contacts A1-A2, A2-A3, B1-B2, and B2-B3. The circuit from motor ST is completed through line 25 to ground line 10. The circuit of the master lane changer is presented in a rest position corresponding to position R1 on the cam chart below with relays IR, OR and CL energized and with the contacts controlled by the corresponding relays up. Cam contacts A2-A3, B2-B3, C1-C2 and E1-E2 are closed. Switch 200 is presented closed, in contact with point 201 and switch 210 is presented closed, in contact with point 211.

Relay OR, illustrated energized, controls contacts 31, 32, 33/34, 34/35 and 214. Relay OL, illustrated de-energized, controls contacts 36, 37, 38/39, 39/40, 41, 42/43 and 43/44. Relay IR illustrated energized, controls contacts 45, 50, 51, 52 and 204. Relay IL, illustrated deenergized, controls contacts 53, 54/55, 55/56, 57, 58/59 and 59/60. Relay G, illustrated deenergized, controls contacts 61, 62 and 63. Relay CL, illustrated energized, controls contacts 64 and 65. Relay OGR illustrated deenergized, controls contacts 70 and 71 while relay IGR shown deenergized, controls contacts 72 and 73.

Lines MIG, MOG, and MCL are output lines of the master lane changer. Lines GI and GO, associated with lines MIG and MOG respectively are also output lines of the master lane changer.

As seen in FIG. 1 the lines MIG, MOG and MCL connect the master lane changer electrically with the local lane changer and lines GI and GO connect the master lane changer electrically with the detector selector.

In FIG. 1 the local lane changer is illustrated in block form as a rectangle lettered LLC while the detector selector is illustrated in block form as a rectangle lettered DS.

The broken line H1 which appears across FIG. 2 and FIG. 7 shall be explained below.

Below the circuit diagram illustrated as FIG. 2 is a cam chart which indicates the relative opening and closing positions of the several cam contacts with relation to the time of one complete revolution of the cam shaft.

The length of time of one revolution depends upon the type of thoroughfare controlled, the distance between signals, the method of clearance to be employed, the amount of clearance time desired and the length of time of the minimum green period desired.

The space between the vertical lines forming the left side and the right side of the cam chart represents an amount of time equal to one complete rotation of the cam shaft. On the left side are the letters and numbers A1-A2, A2-A3, B1-B2, B2-B3, C1-C2, D1-D2, E1-E2 and E2-E3 which represent the eight (8) pairs of cam contacts associated with the cam shaft. The same letters and numbers are used to identify the cam contacts as are used in the circuit drawing as seen in FIG. 2 above, for convenience of identification.

The horizontal line to the right of each letter and number representing a pair of cam contacts represents the amount of time, relative to the time of one cycle, that the pair of cam contacts are closed and at what relative position in the cycle such closure is made. The short vertical line on the horizontal lines are used to emphasize the beginning and the end of the period of closure. Where no horizontal line appears during any part of the cycle, it is an indication that such cam contact is open.

The shaded vertical areas R1 and R2 indicate the two rest positions of the cam shaft. R1 indicates a rest or stop period when the signal lights will show red in both directions on the reversible lane, according to the description offered herein. R2 indicates a rest or stop period when the use of the reversible lane will be accorded to

one directional flow of traffic, as determined by the system and apparatus.

On the lower left the words "Signal Sequence" refer to the line to the right of the words. The horizontal line is separated into shorter segments by short vertical lines. The short segments represent periods of time, relative to the complete cycle time of the cam shaft, that the several combinations of signal lights will be shown. G/R indicates a green signal showing in one direction and a red signal showing in the opposite direction. During this phase the use of the reversible lane will be granted to one directional traffic flow, the other directional flow being denied use of the reversible lane.

Y/R indicates a yellow signal showing in one direction and a red signal showing in the opposite direction. During this phase the yellow signal will be shown to the traffic that had last been granted use of the reversible lane while the red signal will remain illuminated against the other directional traffic flow. This phase may be called a clearance phase since this would be the time in the cycle employed to clear the reversible lane for the next phase. R/R indicates the all-red phase when a red signal is showing to each directional traffic flow thereby keeping all traffic off the reversible lane.

The period G/R may be the inbound phase or the outbound phase as determined by which directional traffic flow is granted use of the reversible lane.

Signal control circuit diagram of FIG. 3

FIG. 3 herein illustrates a circuit diagram of a signal control circuit which may be represented in block form as rectangle LLC in FIG. 1. FIG. 3 may also serve as a signal control circuit that may be associated with FIG. 10.

The lines MIG, MOG and MCL represent input alternating current power lines and may represent the lines similarly labeled extending from the block MLC in FIG. 1 or may represent the lines similarly labeled and represented as extending from the circuit diagram in FIG. 10. The lines MIG, MOG and MCL may supply power for relays IGL, OGL and GY respectively. Line MIG may supply power to relay IGL, the circuit being completed via lead 81 and 80 to the common ground 100. Line MOG may supply power to relay OGL the circuit being completed via leads 82 and 80 to ground 100. The line MCL may supply power to relay GY the circuit being completed via lead 83 and 80 to ground 100.

The relays IGL and OGL are illustrated deenergized and the relay GY is illustrated energized. This condition of the relays IGL, OGL and GY may be the normal condition of the relays and circuitry of FIG. 3 when associated with the master lane changer of FIG. 2 with the master lane changer in its rest position R1, as illustrated in FIG. 2 herein.

The relay IGL in FIG. 3 controls contacts 101/102, 102/103, 104/105 and 105/106. The relay OGL in FIG. 3 controls contacts 111/112, 112/113, 114/115 and 115/116. Relay GY in FIG. 3 controls contacts 121/122, 122/123, 124/125 and 125/126.

The use of switches SW1 and SW2 will be described below.

The broken line boxes FL1 and FL2 represent circuit interrupters or flashers that may provide flashing signals and are in one of the circuits for the yellow signals. The use of these flashers will be explained below.

The inbound signal lamps IGS, IYS and IRS, green (G), yellow (Y) and red (R) respectively may be illuminated by the 120-volt alternating current represented by a plus in a circle. Circuits are completed from the input line 110 to ground line 100 through the several contacts controlled by the relays IGL, OGL and GY, and the various signal lamps to illuminate one of the inbound signal lights, as explained hereinafter.

The outbound signal lamps OGS, OYS and ORS may be similarly illuminated through separate circuits, as explained below.

The signal lamps IGS, IYS and IRS may represent the inbound signal lamps that are represented in FIG. 1 and identically labeled, extending from the left side of block LLC.

5 The signal lamps OGS, OYS and ORS may represent the outbound signal lamps that are represented in FIG. 1 and identically labeled, extending from the right side of block LLC.

Generally, when only relay IGL is energized as by 10 energization of lead MIG, a circuit is completed to illuminate signal lamp IYS while a second circuit illuminates signal lamp ORS. The combination of relays IGL and GY energized, as by energization of leads MIG and MCL, complete circuits to illuminate signal lamps

15 IGS and ORS. When only relay OGL is energized as by energization of lead MOG signal lamps IRS and OYS are illuminated. The combination of relays OGL and GY energized, as by energization of leads MOG and MCL, cause illumination of signal lamps IRS and OGS.

20 When relay GY is alone energized, as by energization of lead MCL, as illustrated in FIG. 3, or when relays IGL and OGL are both energized with relay GY deenergized, or when all three relays are deenergized the signal lamps IRS and ORS are illuminated, when the switches SW1 and SW2 are positioned as illustrated.

Comparison of lane changers of FIG. 2 and FIG. 10

It should be noted that although during normal traffic condition periods the lane changing unit of FIG. 2 keeps its output leads MIG and MOG deenergized, as will be more clearly described below, the alternate form of lane changing unit, illustrated in FIG. 10 maintains both leads MIG and MOG energized during comparable periods. Thus both lane changer units, although providing opposite outputs under similar traffic conditions, may cause to provide similar signal display to traffic on the roadway.

With switch SW1 and switch SW2 in contact with junction 107 and junction 108 respectively and the relays IGL and OGL both energized, as in the normal traffic condition of the alternate lane changing unit, FIG. 10, circuits may be completed to illuminate signal lamps IYS via switch SW1, junction 107 and flasher FL1 while signal OYS is illuminated via switch SW2, junction 108 and flasher FL2.

This arrangement of the switches SW1 and SW2 of FIG. 3 may provide flashing yellow signals to both inbound and outbound traffic during normal traffic conditions.

The flashing yellow signals may indicate to traffic that the reversible lane may be used by both inbound and outbound traffic for "passing only," when safe.

It may be desirable to provide a flashing yellow signal at any time the yellow signal is illuminated. This may be accomplished by moving the flasher so that its electrical location is adjacent to the yellow lamp. The combination of relays OGL and GY when energized cause the illumination of signals IRS and OGS. When relay GY is alone energized as illustrated in FIG. 3, or all three relays are energized or all three relays are deenergized 60 the signals IRS and ORS are illuminated.

Detector selector circuit diagram of FIG. 4

FIG. 4 is a circuit diagram of the detector selector. At the top of the figure, illustrated as a pair of open contacts, are two vehicle actuated detector devices IDD and ODD, for example. These two detector units are comparable to the two detector units, as seen in FIG. 1, in center lane L2 of the roadway RY labeled IDD and ODD. The detector selector is also illustrated in block form 65 labeled DS in FIG. 1. Lines IDL and ODL of FIG. 4 are comparable to the similarly labeled lines in FIG. 1. The lines GI and GO of FIG. 4 are also seen in FIG. 1 identically labeled.

The relay RDI controls contact DS1 and relay RDO 70 controls contact DS2. Line GI supplies an A.C. input

to relay RDI and the circuit is completed through lines 131 and 131' to a common ground line 130 while line GO supplies an A.C. input to relay RDO which circuit is completed through line 131' to ground line 130.

Line IDL supplies an input from the detector selector DS to the inbound cycle selector ICS, as shown in FIG. 1, the circuit from ground 130 is completed through lines 132' to 132, detector unit IDD, contact DS1 to line IDL. Line ODL supplies an input from the detector selector DS to the outbound cycle selector OCS, as shown in FIG. 1, the circuit from ground 130 is completed through line 132', detector unit ODD, contact DS2 to line ODL.

Detector switching circuit diagram of FIG. 5

FIG. 5 is a circuit diagram of a detector switching unit arranged for use with a single detector CD. The two detector circuits are controlled by the relays SDI and SDO, which relays control contacts in the two detector circuits. Power is supplied from line IDL to contact DS11, when closed, to contact DS12/DS13, when closed to the detector CD. The detector circuit is complete through line 165 to a common ground line 166. The other detector circuit is powered by an input through line ODL to contact DS13/DS14, when closed to detector CD and is completed through line 165 to the common ground line 166. Relay SDI is energized by input power through line GI and the circuit is completed through lines 168 to 167 to ground line 166. Relay SDO is energized by input power through line GO and the circuit is complete through line 167 to ground line 166.

The circuit in FIG. 5 is presented with both relays deenergized and both detector circuits open.

Alternate form of lane changing system of FIG. 6

FIG. 6 represents in form another lane changing system differing somewhat from the lane changing system of FIG. 1.

For reasons of convenience and simplification those units in FIG. 1 and in FIG. 6 that are identical are identified with the same numbers and/or letters in both figures.

Referring to FIG. 6 in more detail, a roadway RY is illustrated by two solid horizontal lines across the top of the figure. The roadway RY is separated into three lanes L1, L2 and L3 by two broken lines inside the two solid lines. The roadway section illustrated may be part of a street, highway or thoroughfare for example through which extends a reversible center lane.

On the roadway are three traffic actuated detector units; ID represents a detector in lane L1 that would detect inbound traffic in lane L1 and OD represents a detector in lane L3 that would detect outbound traffic in lane L3. BD illustrates a bi-directional detector that is set in lane L2 and is used to detect both inbound and outbound traffic when either inbound or outbound traffic has been granted use of the center lane.

The detector units ID and OD could be either directional or non-directional type vehicle detectors.

The detector unit ID in the inbound traffic lane L1, actuated by inbound traffic, is connected to the cycle selector ICS, which cycle selector will measure or count inbound vehicle traffic in lane L1 during traffic sampling time periods. Detector ID and cycle selector ICS of FIG. 6 are comparable to detector ID and cycle selector ICS as seen in FIG. 1 and are similarly labeled for convenience.

Detector OD, in the outbound traffic lane L3, actuated by outbound vehicle traffic, is connected to the cycle selector OCS, which cycle selector will measure or count outbound vehicle traffic in lane L3 during traffic sampling time periods. Detector OD and cycle selector OCS of FIG. 6 are comparable to detector OD and cycle selector OCS as seen in FIG. 1 and are similarly labeled for convenience.

Detector unit BD, located in lane L2, represents a bi-directional detector that may be actuated by inbound or

outbound traffic, in center lane L2. The detector BD is connected to the self-selecting detector selector BDS. The self-selecting detector selector is connected to the cycle selector ICS by line IDL and to the cycle selector OCS by line ODL. The cycle selector ICS is connected to the system selector MC by six lines AI, BI, CI, DI, EI and FI while the cycle selector OCS is connected to the system selector MC by six lines AO, BO, CO, DO, EO and FO. The system selector MC is connected to the lane changer LC by two lines IG and OG. These lines, as will be completely explained hereinafter, supply the input for certain relays in the lane changer. To the left of the lane changer LC is illustrated a group of three signal lights IGS, IYS and IRS. These signal lights represent a group of lights that control inbound traffic in the reversible lane. On the right of the lane changer is a similar group of signal lights OGS, OYS and ORS that represent signal lights that would control outbound traffic in the center or reversible lane. Both groups of signal lights in FIG. 6 are similar to the similarly labeled signal lights in FIG. 1.

The letters inside the signals represent R for red, Y for yellow and G for green.

The general description of FIG. 7 will be omitted at this time but will be presented later in the specification.

Self-selecting detector selector circuit diagram of FIG. 8

FIG. 8 is a circuit diagram of the self selecting detector selector that is represented in block form in FIG. 6 and labeled BDS. Through the use of a bi-directional pressure sensitive vehicle detector and the circuitry illustrated, the direction in which a vehicle is traveling as it passes over and actuates the bi-directional detector may be employed to determine to which cycle selector, ICS or OCS, the detection impulse is to be channeled.

At the top of FIG. 8 is one type of bi-directional vehicle detector unit BD, represented by a cross section view of the bi-directional detector with a common base plate GP and two upper contact plates PI and PO. Relays IDR and ODR are energized from an A.C. input, represented by a plus in a circle, through line 170. The completion of the relay circuit depends upon the position of the contacts above the relay. The circuit is completed through these contacts to the plates of the detector, depending upon which contact plate either PI or PO is first closed by pressure, to the ground plate GP to line 171 to ground line 175. The lines IDL and ODL, which lines may be similar to the identically labeled lines in FIG. 6 are input lines to the cycle selectors ICS and OCS respectively and the circuit is completed to ground line 175, which is here considered to be a common ground, through contact DS23 and lines 173 and 174 for line ODL and contact DS27 and line 174 for line IDL.

The relay ODR controls contacts DS20/DS21, DS21/DS22 and DS23 while relay IDR controls contacts DS24/DS25, DS25/DS26 and DS27.

Lane changing system with plural interlinked individually reversible interior lanes—FIG. 9

FIG. 9 represents in block diagram form another alternate form of lane changing system in which two adjacent interior lanes of a multi-lane roadway serving bi-directional traffic, may be individually controlled so that the reversible lanes are positively allocated to one direction of traffic, or the other direction of traffic except during transition of one or both reversible lanes.

Individual control over each lane of two adjacent interior reversible lanes, L22 and L33 is obtained through use of two master lane changers MLC1 and MLC2, each partially controlled by the other master lane change and both controlled in common by a system selector or master controller MC.

By adjustment of certain switches, as more fully described below, during average or balanced traffic conditions the lane L22 will be allocated to one direction of traffic and the lane L33 will be allocated to the other di-

rection of traffic so that, for example, lanes L11 and L22 will be allocated to inbound traffic and lanes L33 and L44 will be allocated to outbound traffic.

During outbound peak traffic conditions lanes L22, L33 and L44 will be allocated to outbound traffic while lane L11 remains allocated to inbound traffic and during inbound peak traffic conditions lanes L11, L22 and L33 will be allocated to inbound traffic while lane L44 remains allocated to outbound traffic.

Each master lane changer may individually control a detector selector that is associated with the reversible lane over which that master lane changer exerts control.

Alternate form of master lane changer of FIG. 10

FIG. 10 is a schematic circuit diagram of an alternate form of master lane changer or lane changing unit that may be employed in a lane changing system, as illustrated in FIG. 1 for example, with FIG. 10 illustrating circuitry that may be found in the block MLC.

As more fully described below, the lane changing unit of FIG. 10 is illustrated as being controlled via leads IG and OG which lead may be outputs of a master controller, such as block MC in FIG. 1, for example.

Output leads of the lane changing unit may be the leads MIG, MOG and MCL or other outputs as described below that may extend to a signal control circuit, as for example block LLC, in FIG. 1.

Description of system of FIGS. 1, 2 and 3 in various assumed conditions

Referring more fully to the block diagram of FIG. 1, a multi-lane roadway RY, including lanes L1, L2 and L3 is illustrated at the top of the diagram representing a roadway of three or more traffic lanes serving bi-directional traffic. Lane L1 may be permanently allocated to inbound vehicle traffic and lane L3 may be permanently allocated to outbound vehicle traffic. Lane L2 may, during average or balanced traffic periods, be kept vacant of vehicle traffic and thus may serve as a buffer or safety zone between inbound traffic and outbound traffic, or may be allocated to both directions of traffic flow as a "passing lane only," as desired. During peak traffic periods, use of lane L2 will be accorded to the peak traffic flow whether it be inbound or outbound traffic.

The signal lights that control the directional traffic flow will be assumed to be overhead signals, over the center of each individual lane. The signals over the center of lane L1 will show green for inbound traffic and red for outbound traffic as this lane will always be accorded to inbound traffic and, for purposes of explanation, never accorded to outbound traffic. The signal light over the center of lane L3 will show green for outbound traffic and red for inbound traffic as lane L3 will always be accorded to outbound traffic and never to inbound traffic. It may be desired to use descriptive signs over lanes L1 and L3 or to leave the lanes unsignalized and unidentified, as desired.

It should be understood that although lanes L1 and L3 are illustrated as one lane each they may each be two lanes or more each, according to the width of the roadway controlled. The signal lights over lanes L1 and L3 may very well be a single double-faced signal light showing green in one direction and red in the other direction. These signals will not change for purposes of this explanation.

Lane L2, the center lane, will have sets of three signals visible to each directional flow of traffic. These signals will be the set IGS, inbound green signal, IYS, inbound yellow signal, and IRS, inbound red signal, located overhead, in the center of the lane position and visible to inbound traffic. The set of signals OGS, outbound green signal, OYS, outbound yellow signal, and ORS, outbound red signal, will be located overhead in the center of the lane position visible to outbound traffic. The two sets of signals will be placed, for description purposes, back to back, overhead in the center of lane L2 at a site along

the highway RY between two intersections so as to eliminate possible confusion with intersection control signals.

The vehicle actuated detector unit may be placed at any point or points along the highway. However, for purposes of illustration, it will be assumed that the detectors will be centrally located along the length of the highway. The detector ID, used to detect inbound traffic in lane L1, and the detector IDD, used to detect inbound traffic in lane L2, will be placed in the respective lanes and in a line perpendicular to the longitudinal line of the highway RY similar to the illustration in FIG. 1. The detector OD, used to detect outbound traffic in lane L3, and the detector ODD, used to detect outbound traffic in lane L2 will be placed in the respective lanes also in a line perpendicular to the longitudinal line of the highway RY as illustrated in FIG. 1. The inbound detectors ID and IDD, and the outbound detectors OD and ODD may be placed in close proximity to each other.

The physical location of the detector selector DS, the two cycle selectors ICS and OCS, the system selector, MC and the master lane changer may be any convenient place. They may be placed in close proximity to the highway RY or away from the highway whichever may be desired. The local lane changer LLC may also be located with the above mentioned equipment or located at the side of the highway RY in close proximity to the signal lights.

Assuming master lane changer at rest in position R1 with red signals in both directions in reversible center lane

In the following description it will be originally assumed that the master lane changer MLC is at rest in position R1, as presented in FIG. 2, with power applied to the output line MCL to the local lane changer LLC.

The signal lights, over center lane L2 of roadway RY, as controlled by the local lane changer, will show red signals illuminated to both inbound traffic and outbound traffic so that use of center lane L2 is denied to both inbound and outbound traffic.

According to the present assumed conditions the assumed system maintains center lane L2 as a buffer lane or safety zone, during average or non-peak traffic conditions, between the inbound and outbound traffic flows.

With all traffic restricted from the center lane there will be no actuations on either detector IDD or ODD.

However, the inbound traffic in lane L1 will be crossing over detector ID causing actuation of the detector ID and the outbound traffic in lane L3 will be crossing over detector OD causing actuations of the detector OD.

The detector ID is connected to the cycle selector ICS from where the detector ID receives its power, while the detector OD is connected to the cycle selector OCS from where the detector OD receives its power.

FIG. 1 and FIG. 6 are illustrated in single line, block form and although no specific source of power or ground connection is illustrated it should be understood that local power is applied to the individual units of the system as illustrated in the individual circuit diagrams and that ground returns complete the circuit where necessary.

The cycle selectors ICS and OCS, as more fully described in Patent No. 2,288,601, are arranged for operation with an input supply of 120-volt alternating current. An output lead supplies current to the respective detector with the circuit completed through the detector and returned through a common ground line. The cycle selectors may be arranged for two or more detectors each, in such case the detectors IDD and ODD would be connected to the respective cycle selector via separate circuits, as illustrated in FIG. 1. If the cycle selectors were arranged for one detector, an additional detector, the detector IDD for example, may be connected in parallel with detector ID to the cycle selector ICS via line IDL to the circuit of detector ID and the detector ODD for example, may be connected in parallel with

detector OD to the cycle selector OCS via line ODL to the circuit of detector OD.

Instead of each cycle selector incorporating a separate timer for setting up the traffic sampling periods as in Patent No. 2,288,601 previously mentioned, for purposes of the present invention it is preferable to employ a common timer to time the traffic sampling time period for both of the cycle selectors ICS and OCS as has been fully explained in Patent No. 2,542,978 heretofore mentioned.

In FIG. 1 herein each of the cycle selectors ICS and OCS have been illustrated as having six cycle position output lines AI, BI, CI, DI, EI, and FI for cycle selector ICS and AO, BO, CO, DO, EO, and FO for cycle selector OCS. These six output lines correspond to the six cycle positions A, B, C, D, E, and F of the Patent No. 2,288,601 referred to. In the present embodiment the output lines of each cycle selector, six lines for each, are individually connected to separate terminals in the system selector MC, having twelve terminals in all.

Each of the cycle selectors connects A.C. power to one of its output circuit terminals which corresponds to the cycle position it is then selecting, and maintains power on this output terminal until another output terminal is selected at the end of one of the subsequent traffic sampling time periods.

As is more fully explained in Patent No. 2,542,978, the inbound cycle selector ICS will apply electric power on one of its cycle position output circuits of its AI to FI cycle scale in accordance with the cycle it is selecting at the moment in response to its measurement of traffic actuating the traffic detector ID. Correspondingly cycle selector OCS will apply power on one of its six cycle position circuits of its AO to FO cycle scale in accordance with the cycle it is selecting in response to its measurement of traffic actuating the detector OD. Thus these circuits from the cycle selectors provide input control circuits to the system selector MC and accordingly the system selector provides power on its appropriate output circuits IG and OG to provide selection of the appropriate input power to the master lane changer MLC.

The output circuits IG and OG, as seen in FIG. 1 illustrated as extending from the bottom of the system selector MC, represent circuits which are individually energized to provide power to certain relays, IR and OR, in the master lane changer MLC, as seen in FIG. 2.

As will be more fully described hereinafter, this arrangement permits the choice of four different cycle control combinations by these two circuits IG and OG. With power on line IG only, relay IR will be energized while relay OR remains deenergized and with power on line OG only, relay OR will be energized while relay IR remains deenergized. The third combination would be the case of power on both lines IG and OG to energize both relays IR and OR while the fourth combination would deenergize IG and OG thereby keeping both relays IR and OR deenergized.

Assuming approximately equal traffic inbound and outbound with master lane changer at rest in position R1

Assuming the master lane changer to be at rest as heretofore stated, let it be assumed that the traffic flow in both directions along the roadway RY illustrated in FIG. 1, is light and that the number of vehicles traveling in either direction is approximately equal. Referring in particular to FIG. 1, let it also be assumed that the detectors ID and OD have been detecting the presence of vehicles so that the corresponding cycle selectors have both selected a cycle. Thus cycle selector ICS is maintaining powers to the system selector MC via line BI for example and cycle selector OCS is maintaining power to the system selector MC via line BO for example during the present traffic sampling time period. Let it be fur-

ther assumed that the cycle selectors are now sampling the present respective traffic flows.

With the cycle selectors having both selected similar cycle positions, BI and BO, the system selector maintains both the output lines IG and OG energized, which lines maintain both relay IR and OR energized. Referring to FIG. 2 with relay IR and OR energized and the master lane changer MLC at rest in position R1 as shown on the cam shaft chart, relay CL is energized via a circuit that may be traced from the A.C. input 15 through line 18, closed cam contacts C1-C2, line 19 to the coil of relay CL, line 20, line 10' to ground line 10. Relay IR is energized from the system selector MC through line IG, switch 210, point 211, point 216, the coil of relay IR to lines 11 and 10' to ground line 10. Relay OR is energized from the system selector MC through line OG, switch 200, point 201, point 206, the coil of relay OR to lines 12 and 10' to ground line 10. With both relays IR and OR energized, relays IL and OL are deenergized since contact 32 of relay OR, which has been opened by energized relay OR, breaks the energizing circuit for relay IL and contact 45 of relay IR, opened by energized relay IR, breaks the energizing circuit for relay OL. Relay G is deenergized since the cam contacts D1-D2, in its energizing circuit, are open. The timing motor ST is stopped since both contact 57, of relay IL, and contact 41, of relay OL, are open and fail to complete a circuit to the A.C. input at line 15 to energize the timing motor ST.

With relays OL and IL deenergized, relays OGR and IGR are also deenergized.

Relay CL, now energized, closes its contact 65 which contact completes the output circuit MCL of the master lane changer to A.C. input 15. The output lines MIG and MOG of the master lane changer have no power applied to them since both relays OGR and IGR are deenergized and certain of their respective contacts are open to maintain lines MIG and MOG deenergized.

Output lines MIG, MOG, and MCL of the master lane changer supply power to the relays IGL, OGL, and GY, respectively, of the local lane changer as seen in FIG. 3.

Following the system through it is found that the relay GY, seen in FIG. 3, is energized from the output power of the master lane changer via line MCL through the coil of relay GY, lines 83 and 80 to ground line 100.

Relay GY closes its contacts 121/122 and 124/125 and opens its contacts 122/123 and 125/126.

With relays IGL and OGL both deenergized A.C. power from input line 110 flows through the line 84 to contacts 102/103 of relay IGL to line 85 to the red signal IRS to ground 100 thereby illuminating the red signal IRS to inbound traffic indicating that inbound traffic shall not use center lane L2. A.C. input power is also applied through the lines 110, and 86, contacts 115/116 of relay OGL to line 87 to the red signal ORS to ground 100 thereby illuminating the red signal ORS to outbound traffic indicating that outbound traffic shall not use center lane L2 thereby maintaining center lane L2 as a buffer zone between the two flows of directional traffic.

It should be noted that the signals IGS, inbound green, IYS, inbound yellow, IRS, inbound red, OGS, outbound green, OYS, outbound yellow and ORS, outbound red are externally located in the system but are illustrated in FIG. 3 as interior elements for convenience of illustration.

Since there is no power on output lines MIG and MOG of the master lane changer in FIG. 2, there is also no power in output lines GI and GO. The output lines GI and GO supply no power to the detector selector DS, illustrated in FIG. 4, so that both relays RDI and RDO are deenergized thereby keeping the detectors IDD and ODD in center lane L2 without power which when applied would be applied via lines IDL and ODL from the cycle selectors through contacts of relays RDI and RDO to each detector respectively.

Operation of master lane changer from rest position R1 to rest in position R2—assuming traffic change from approximately equal inbound-outbound to heavier inbound

Let it be assumed that traffic conditions along the controlled highway remain relatively constant and both inbound and outbound traffic are restricted to lanes L1 and L3 respectively. After an appreciable time inbound traffic traveling in lane L1 increases so that at the end of a subsequent traffic sampling period cycle selector ICS decides to change positions and selects the next higher cycle position CI for example, while cycle selector OCS still selects the same cycle position BO for example, since outbound traffic remains relatively constant.

Assuming that the system selector will react only when there is a difference of two or more cycle positions between the cycle selectors, traffic remains restricted from lane L2.

Increased inbound traffic counted during the following traffic sampling time period causes cycle selector ICS to select a still higher cycle position so that now for example the line DI is energized by cycle selector ICS while cycle selector OCS still energizes line BO.

The two cycle selectors would now be two cycle positions apart energizing non-corresponding input terminals in their respective bank of input terminals to the system selector MC. The system selector MC would deenergize the output line OG and cause relay OR, in the master lane changer MLC, seen in FIG. 2, to become deenergized while the output line IG remains energized keeping relay IR in the master lane changer energized.

Relay OR closes its contact 32 causing relay IL to be energized via a circuit from the A.C. input line 15 through line 74, contact 61 of G relay, contact 64 of CL relay, line 66, contact 32 of OR relay, contact 50 of IR relay, line 67, the coil of IL relay, line 16, line 10' to ground line 10.

With IL relay energized, contact 57 of IL relay would close and complete a circuit to energize the motor ST through a circuit from A.C. input line 15, line 68, contact 57 of IL relay, line 69, cam contacts B2-B3, cam contacts A2-A3 the motor ST, line 25 to ground line 10. The motor ST would advance the cam shaft in its cycle, out of the rest position R1, open its cam contacts B2-B3 and close its cam contact B1-B2 to maintain power from A.C. input line 15 through line 18 to point 18', cam contacts B1-B2, cam contact A2-A3 through the coil of the motor ST, line 25 to ground line 10 to keep the motor running, thus advancing the cam shaft in its cycle.

Relay IL would close its contact 53 to prepare a lock-in circuit to keep itself energized.

The cam shaft would be advanced by the motor ST and close cam contacts D1-D2, thus completing the energizing circuit for relay G from the A.C. input line 15, through line 18, cam contacts D1-D2, line 21, the coil of relay G, line 22, line 10' to ground line 10.

The relay G would close its contact 62, which contact is known by those skilled in the art as a make-before-break contact composed of contacts 61 and 62, thereby completing the lock-in circuit for relay IL from the A.C. input line 15, line 74, contact 62 of G relay, contact 53, line 67 to the coil of relay IL, line 16, line 10' to ground line 10.

The relay IL, when energized, closes its contacts 58/59 to prepare a circuit to energize relay IGR. With relay G energized, its contact 63 is closed to complete the circuit to energize relay IGR from the A.C. input line 15 through line 68, contact 63 of relay G, line 75, contact 43/44 of relay OL, contact 58/59 of relay IL, the coil of relay IGR, line 24 to the ground line 10.

Relay IGR opens its contact 72 to insure that the output line MOG is not energized and closes its contact 73 completing a circuit from A.C. input line 15, through line 76, contact 71 of relay OGR, contact 73 of relay IGR to

energize the output line MIG. The output line MCL is energized from the A.C. input through line 15, contact 65 of relay CL to line MCL.

Now both output lines MCL and MIG are energized with output line MOG deenergized.

Referring now to FIG. 3 both relays IGL and GY would now be energized. Relay IGL is energized via the energized input line MIG through the coil of the relay IGL, line 81 to line 80 to the ground line 100 while relay GY remains energized from the energized input line MCL as previously explained.

The relay IGL would close its contact 101/102 and complete a circuit from A.C. input line 110 through line 84, contact 101/102 of relay IGL, contact 112/113 of relay OGL, contact 121/122 of relay GY to ground line 100 thereby illuminating the green inbound signal while the red outbound signal remains illuminated through a circuit from the A.C. input 110 through line 86, contact 115/116 of relay OGL, line 87, signal ORS to ground line 100.

With output line MIG in the master lane changer energized, the output line GI is also energized through a circuit, as seen in FIG. 2, from the A.C. input via lines 15 and 76, contact 71, contact 73 to line GI. As seen in FIG.

25 4, the circuit diagram of the detector selector, also illustrated in FIG. 1 as a rectangle designated DS, the output line GI of the master lane changer is the input line supplying A.C. power to the relay RDI through its coil to line 131, line 131' to ground line 130. The input line GO, supplying power to relay RDO of the detector selector, would be deenergized so that relay RDO would be deenergized.

Relay RDI would close its contact DS1 to complete the input power line from the inbound cycle selector ICS through line IDL, contact DS1 of relay RDI to detector 35 IDD, in center lane L2, the circuit being completed through lines 132, 132' to ground line 130.

With power applied to the detector IDD, the inbound traffic traveling in center lane L2, now receiving a green signal, would actuate the detector IDD and the actuations 40 would be received by the inbound cycle selector, ICS, so that an accurate sampling of the inbound traffic flow is received by the inbound cycle selector. The detector ODD also in center lane L2 would not have power applied to it so that it would not be effective at this time.

The motor ST, in FIG. 2, continues to advance the cam shaft in its cycle until the cam contacts A2-A3 open and A1-A2 close. When cam contacts A2-A3 open and A1-A2 close, the energizing circuit for the motor ST opens and the motor ST stops in the rest position, R2, as indicated on the cam chart below the circuit diagram in FIG. 2. The A.C. power from line 15, through line 18 to contact 54/55 of relay IL would be broken by open contact 52 of relay IR to stop the motor ST while the signals remain green for inbound traffic in lane L2 thereby granting inbound traffic use of center lane L2, as well as lane L1, while outbound traffic is restricted to lane L3 by a red signal showing for outbound traffic over lane L2.

So long as inbound cycle selector ICS selected a cycle of two or more positions higher than the position selected by 60 out-bound cycle selector OCS at the end of subsequent traffic sampling periods, the lane changing system will remain in the position in which it is now assumed. It should be understood that the system selector may be adjusted to respond to a difference of one position between the cycle 65 selectors or more than one position. Here it has been assumed that the system selector shall respond initially to a difference of two or more positions between the cycle selectors.

During the traffic sampling time periods with the lane changing system in the presently assumed position, inbound cycle selector ICS is receiving actuations from two detectors, ID and IDD, both actuated by inbound traffic while outbound cycle selector OCS is receiving actuations 70 from one detector OD, actuated by outbound traffic.

Operation of master lane changer from rest in position R2 to position R1—assuming decrease in inbound traffic from heavier inbound to approximately equal inbound and outbound

Let it be assumed that the numerically superior inbound traffic decreases while the number of outbound vehicles remains approximately as previously assumed so that again the amount of inbound vehicles traveling over the highway RY and the amount of outbound vehicles traveling over the highway are, for purposes of explanation, approximately balanced numerically.

The decrease in the volume of inbound traffic over the lanes L1 and L2 would become apparent to inbound cycle selector ICS through reduced actuations of detectors ID, in lane L1, and IDD, in lane L2, while the relatively constant volume of outbound traffic in lane L3 would be apparent to outbound cycle selector OCS through actuations of detector OD, in lane L3.

The volumes of the opposing traffic flows would be reflected in the cycle positions selected by the respective cycle selector at the end of a traffic sampling time period.

The resulting change of relative cycle positions will cause system selector MC to energize both output lines IG and OG. Energization of both lines IG and GO cause the master lane changer MLC to start the motor ST and thereafter deenergize its output lines MIG, MOG, GI and GO. Signal changes are accomplished and upon deenergization of lines MIG and MOG, both red signals are illuminated. Upon deenergization of both lines GI and GO both detectors IDD and ODD are removed from the counting circuits of the associated cycle selectors.

The sequence of change to restrict traffic from the center lane begins by extinguishing the green inbound signal IGS and illuminating the yellow or clearance inbound signal IYS for traffic in lane L2 while the red outbound signal ORS remains illuminated. Yellow signal IYS will remain illuminated for a predetermined time, as set by adjustment of the cams on the cam shaft in the master lane changer. At termination of the clearance period the yellow signal will be extinguished and the red inbound signal IRS will be illuminated.

Thus with both red signals IRS and ORS illuminated to the traffic flow each controls the cam shaft will reach its rest position R1 and remain at rest until a change in relative cycle positions is accomplished at the end of a subsequent traffic sampling time period.

At the end of a traffic sampling time period, during which time the reduced actuations were received, the inbound cycle selector ICS determines a cycle position in accordance with the volume of inbound traffic flow in lanes L1 and L2. The outbound cycle selector OCS determines a cycle position in accordance with the volume of outbound traffic flow in lane L3. It has been assumed that the both traffic flows are approximately balanced so that the cycle position BI and BO for example would be selected by the respective cycle selectors.

The output circuits represented by BI and BO from the respective cycle selectors ICS and OCS would be energized to deliver power to the comparable input terminals in the system selector MC. The system selector MC maintains power on its output line IG and restores power to its output line OG.

During the preceding period, as previously described, relays CL, G, IL and IR of the master lane changer MLC, FIG. 2 had been energized. With power from the system selector MC now applied to its output line OG, relay OR is energized as previously described. Contact 33/34 of relay OR is closed to complete an energizing circuit for motor ST, from A.C. input line 15, line 18, point 18', contact 51 of relay IR, contact 33/34 of relay OR to line 83 to cam contact A1-A2 to the coil of the motor ST, through line 25 to ground line 10.

The motor ST advances the cam shaft in its cycle out of the rest position R2 and cam contacts A1-A2 open as cam contacts A2-A3 close. The green inbound signal

and the red outbound signal hold traffic until the cam shaft is rotated to open cam contacts C1-C2, the relative position of the cam action may be observed from the cam chart below the circuit diagram in FIG. 2. The opening of cam contact C1-C2 breaks the energizing circuit for relay CL. Deenergized relay CL releases its contact 65 which opens and deenergizes output line MCL of the master lane changer so that now only output line MIG is energized. With line MCL deenergized, the relay GY in FIG. 3 becomes deenergized and the signals in lane L2 change from green inbound to yellow inbound while the outbound signal remains red. The circuit in FIG. 3 to illuminate yellow inbound signal IYS may be traced from the A.C. input 110 through line 84, contact 101/102 of relay IGL, contact 112/113 of relay OGL, contact 122/123 of relay GY, signal IYS to ground line 100.

The yellow inbound signal and the red outbound signal on lane L2 would remain illuminated until the motor ST rotates the cam shaft so that cam contacts D1-D2, as seen in the cam chart in FIG. 2, open. When cam contacts D1-D2 open, the energizing circuit for relay G is broken and relay G releases its contact 62 and breaks the energizing circuit for relay IL.

Deenergized relay IL releases its contact 57 to prepare to deenergize the motor ST when the cam contacts B1-B2 opens and B2-B3 closes.

Contact 63 of relay G is released opening the energizing circuit for relay IGR. Deenergized relay IGR releases its contact 73 to deenergize the output lines MIG and GI.

When the output line MIG becomes deenergized, power to energize relay IGL of FIG. 3 is interrupted and relay IGL becomes deenergized. Relay IGL closes its contact 102/103 causing red signal IRS for inbound traffic on lane L2 to be illuminated. The yellow inbound signal on lane L2 is extinguished by opening contact 101/102.

Signal ORS is maintained illuminated through a circuit previously described and thus both inbound and outbound traffic are restricted from the lane L2.

The cam shaft in FIG. 2 continues to be rotated by motor ST and cam contacts C1-C2 close. The energizing circuit for relay CL is completed, as previously described and energized relay CL closes its contact 65 to apply power to output line MCL.

Although the lane changer MLC energizes relay GY, in FIG. 3, there is no change in the signals displayed on lane L2 at this time.

As output lines MIG and GI become deenergized, relay RDI of the detector selector, FIG. 4, becomes deenergized. Relay RDI releases its contact DS1 and breaks the detector circuit for detector IDD from the output line IDL, from the cycle selector ICS, so that any actuations on detector IDD would no longer affect the inbound cycle selector ICS. The rotation of the cam shaft continues until cam contacts B1-B2 opens and B2-B3 closes thereby breaking the energizing circuit for motor ST at its rest position R1.

The master lane changer will remain in its rest position, R1, so long as both input lines IG and OG remain energized. The system selector MC will maintain the lines IG and OG energized so long as inbound cycle selector ICS and outbound selector OCS select cycle positions that are not more than one position apart, the cycle positions selected depending upon the number of actuations received by the individual cycle selectors from the associated detector during a traffic sampling time period.

Attention is now directed to the cam chart in the lower part of FIG. 2. The length of time necessary to complete one cycle may vary according to the speed of rotation of the motor used to rotate the cam shaft. The preferred time is from six (6) to ten (10) minutes for one complete rotation. The time of one cycle and the setting of the cams determine the minimum time for each signal period.

Referring in particular to the line "Signal Sequence," it may be observed that the cam shaft may rest with red signals illuminated to both inbound and outbound traffic,

at R1 or may rest in R2 and show a green signal to one traffic flow and a red signal to the other. If the cam shaft should come to rest at either R1 or R2, or both, during the course of one cycle such resting would substantially lengthen the time of one cycle by the period in which the cam shaft came to rest. This rest period is determined by relative traffic conditions along the roadway.

The clearance period, during which period a yellow signal is illuminated to one traffic flow and a red signal to the other, does not include a rest position so that the time of the clearance period will remain set, as desired.

The above description disclosed the method and operation resulting in the use of the center lane being accorded to inbound traffic, outbound traffic being restricted therefrom, the clearing of the inbound traffic from the center lane, followed by the restriction of both inbound and outbound traffic from the center lane L2 according to the actuations of the inbound traffic and the outbound traffic individually.

It is necessary to note that should the traffic again be unbalanced in favor of the inbound traffic, the operation of the lane changing system would repeat that which was described above, to accord use of center lane, L2, to the inbound traffic.

Operation of master lane changer from rest in position R1 to rest in position R2—assuming outbound traffic becomes heavier

However, let it now be assumed that the volume of inbound traffic remains approximately the same and the volume of outbound traffic along the highway RY increases.

As the outbound traffic volume increases, there would be additional actuations on the outbound detector OD accordingly, while the actuations on the inbound detector ID would remain constant, due to the constant volume of inbound traffic along the highway as assumed.

The increased outbound traffic actuations would be reflected in outbound cycle selector OCS and, at the end of a subsequent traffic sampling time period in which the increased outbound traffic actuations were received by outbound cycle selector OCS, outbound cycle selector OCS would advance to a higher position in the cycle, for example DO, while the inbound cycle selector ICS, which had received approximately the same volume of actuations during successive sampling periods from its detector ID, due to a constant volume of inbound traffic, would remain on the same cycle position, for example, BI.

The cycle positions selected by the cycle selectors would cause the system selector, MC, to maintain output line OG energized and deenergize output line IG resulting in certain internal reactions in the master lane changer MLC, hereinafter described, to change the signals over the lane L2 so that use of center lane L2 would be granted to outbound traffic signified by a green signal to outbound traffic over center lane L2 and use of center lane L2 denied to inbound traffic, signified by a red signal to inbound traffic over center lane L2.

The output power through circuits BI and DO from the cycle selectors ICS and OCS respectively would be applied as input power to the system selector MC.

Energized output line OG, from the system selector, would maintain power to energize the relay OR in the master lane changer MLC, in FIG. 2, while deenergized output line IG would cause the relay IR, in the master lane changer MLC to drop out.

Relay IR would close its contact 45 to energize relay OL from the A.C. input line 15, through line 74, contact 61 of relay G, contact 64 of relay CL, line 66, contact 45 of relay IR, line 89, contact 31 of relay OR, the coil of relay OL, line 17, line 10' to ground line 10.

Relay OL would close its contact 41 to energize the motor ST through a circuit from the A.C. input line 15, line 68, line 68', contact 41 of relay OL, line 69', line 69

to cam contacts B2-B3, cam contact A2-A3 to the coil of the motor ST, line 25 to ground line 10.

The motor ST being thus energized would revolve the cam shaft and open cam contacts B2-B3 and close cam contacts B1-B2 to complete a circuit from the A.C. input line 15, through line 18, terminal 18', cam contacts B1-B2, cam contacts A2-A3 to the coil of the motor ST, line 25 to ground line 10.

Relay OL would close its contact 42/43 to prepare an energizing circuit for relay OGR.

As the cam shaft continues to revolve, the cam contact D1-D2 would close to complete an energizing circuit for relay G as previously described. Relay G would close its contact 62 to complete an energizing circuit to keep relay OL energized from the A.C. input line 15 through line 74, contact 62 of relay G, line 90, contact 36 of relay OL, the coil of relay OL, line 17, line 10' to ground line 10.

Relay G would close its contact 63 to complete the prepared circuit from the A.C. input 15, line 68, contact 63 of relay G, line 75, line 75', contact 59/60 of relay IL, contact 42/43 of relay OL, the coil of relay OGR to line 23, line 24 to ground line 10, thereby energizing relay OGR.

Relay OGR would close its contact 70 to energize output lines MOG and GO from the A.C. input line 15, through line 76, contact 72 of relay IGR, contact 70 of relay OGR to the output lines MOG and GO.

Now both output lines MCL and MOG to local lane changer LLC would be energized.

Relay OGL in FIG. 3 is energized from the output power line MOG from the master lane changer through the coil of relay OGL, line 82 to line 80 to ground 100 while relay GY is energized by the output power line MCL, the coil of relay GY, line 83 to ground 100. The energizing of both relays OGL and GY would cause an outbound green signal to be illuminated over center lane L2 through a circuit from the A.C. input line 110, through line 86, contact 114/115 of relay OGL, contact 105/106 of relay IGL, line 91, contact 124/125 of relay GY, signal OGS to ground line 100.

The red inbound signal over center lane L2 would remain illuminated through the circuit from the A.C. input line 110, line 84, contact 102/103 of relay IGL, line 85, signal IRS to ground line 100. The outbound red signal ORS is extinguished by the opening of contacts 115/116 of relay OGL.

Output power line GO, from the master lane changer MLC, would energize relay RDO of the detector selector, FIG. 4, through the coil of relay RDO, line 131' to ground line 130. Relay RDO would close its contact DS2 to apply power for the detector circuit from the outbound cycle selector OCS through line ODL, the contact DS2 of relay RDO, detector ODD, line 132' to ground line 130. This completion of the detector circuit to detector ODD in lane L2 would cause the outbound vehicles traveling in lane L2 to be counted by the outbound cycle selector OCS during the traffic sampling time periods when such outbound traffic crosses the detector ODD thereby affording means of obtaining an accurate sampling count of the outbound traffic in both the lanes L2 and L3.

The motor ST in FIG. 2 would advance the cam shaft in its cycle until the cam contacts A2-A3 open and A1-A2 close thus changing the energizing circuit of the motor ST. The energizing circuit would now be broken by contact 39/40 of relay OL which contact would now be open. The motor ST would stop in its rest position R2.

Operation on sudden traffic change from heavier outbound to heavier inbound

There may be occasions when opposing traffic will change greatly with respect to each other, for example, let it now be assumed that the outbound traffic, which heretofore was just considered to be numerically superior to the inbound traffic along the highway, suddenly decreases appreciably while the inbound traffic increases

and becomes numerically superior to the outbound traffic.

Let it be further assumed that this substantial change in the relationship between inbound and outbound traffic results in the cycle selectors reversing their cycle positions so that inbound cycle selector ICS advances from position BI to DI and outbound cycle selector OCS drops from position DO to BO, for example.

It should be noted that in the previous descriptions and assumptions a change of such amplitude was not considered.

Such a change in traffic conditions along the controlled highway would require a complete reversal of center lane L2 from use of the center lane L2 by outbound traffic to use of the center lane L2 by inbound traffic. This reversal is accomplished by a change of signals so that the outbound traffic signals in center lane L2 are changed from a green outbound signal to a yellow outbound signal while the inbound traffic signals remain red. The combination of inbound red and outbound yellow would be followed by a minimum period during which a red signal is displayed to both inbound and outbound traffic. After such minimum period a green inbound traffic signal would be illuminated, the red inbound signal being extinguished, while the red outbound traffic signal remains illuminated, thereby granting use of center lane L2 to inbound traffic.

The reduced volume of outbound vehicle traffic and the increased volume of inbound traffic is reflected, from the detector ID, in lane L1, being actuated by inbound traffic, and the detectors OD in lane L3, and ODD in lane L2, being actuated by outbound traffic and in the selected cycle positions of the respective cycle selectors ICS and OCS. The cycle selectors ICS and OCS would apply power through lines DI and BO respectively to the system selector, MC, which would in turn energize its output line IG and deenergize its output line OG.

Relay OR, in the master lane changer MLC, in FIG. 2, would be deenergized and relay IR in the master lane changer MLC, would be energized through a circuit previously described.

When relay OR becomes deenergized, it releases and closes its contact 34/35 thereby completing an energizing circuit for the motor ST from the A.C. input 15 through line 18, terminal 18', contact 37 of relay OL, contact 34/35 of relay OR, line 88, cam contacts A1-A2, the coil of motor ST, line 25 to ground line 10. Energized motor ST starts rotating the cam shaft, the cam shaft moves out of its rest position, R2, and opens its cam contacts A1-A2 and closes its cam contacts A2-A3 to complete another circuit for motor ST through cam contacts A2-A3 and B1-B2 as previously described.

The cam shaft continues to rotate while the green outbound signal and the red inbound signal over center lane L2 hold until cam contacts C1-C2 open to cause relay CL to become deenergized.

Deenergized relay CL releases and opens its contact 65 to deenergize output line MCL.

Deenergizing output line MCL is reflected in the local lane changer LLC, as seen in FIG. 3, by deenergization of relay GY. When relay GY is deenergized, it opens its contact 124/125 and closes its contact 125/126. This extinguishes the outbound green signal over center lane L2 and illuminates a yellow signal for outbound traffic in lane L2 through a circuit from the A.C. input line 110, line 86, contact 114/115 of relay OGL, contact 105/106 of relay IGL, line 91, contact 125/126 of relay GY, signal OYS to ground line 100. The red inbound traffic signal over center lane L2 remains illuminated as previously described.

The outbound yellow signal over center lane L2 remains illuminated until the cam shaft advances and opens the cam contacts D1-D2.

The opening of cam contacts D1-D2 cause deenergization of relay G. Contacts 62 and 63 of relay G are opened causing deenergization of relays OI and OGR respectively. Deenergized relay OGR opens its contact 70

which contact causes output lines MOG and GO to become deenergized.

With output lines MIG, MOG and MCL, from the master lane changer MLC, deenergized, the relays IGL, 5 OGL, and BY, in the local lane changer, FIG. 3, are deenergized so that the outbound yellow signal would be extinguished and the outbound red and inbound red signals would both be illuminated over center lane L2. Signal ORS is illuminated via a circuit from the A.C. input 110, through line 86, contact 115/116 of relay OGL, line 10 37, signal ORS to ground 100. Signal IRS is illuminated via a circuit from the A.C. input 110, through line 84 contact 102/103 of relay IGL, line 85, signal IRS to ground 100.

15 With output line GO deenergized, the relay RDO in the detector selector DS, FIG. 4, is deenergized. Contact DS2 of relay RDO is opened to break the detector circuit between line ODL and detector ODD in lane L2. At 20 this point the outbound vehicle traffic is counted by actuations on the detector OD in lane L3 and the inbound traffic is counted by actuations on the detector ID in lane L1. Detectors IDD and ODD in lane L2 are both disconnected and unused.

The inbound red signal and the outbound red signal 25 over the center lane L2 would remain illuminated for a minimum period determined by the setting of the cams on the cam shaft.

The motor ST in FIG. 2 would advance the cam shaft 30 in its cycle and the cam contacts C1-C2 would close thereby completing the energizing circuit for relay CL. Relay CL would close its contact 64 thus completing an energizing circuit for relay IL from the A.C. input 15 through line 74, contact 61 of relay G, contact 64 of relay CL, line 66, contact 32 of relay OR, contact 50 of 35 relay IR to the coil of relay IL, line 16, line 10' to ground line 10.

The relay IL would close its contact 57 to prepare an energizing circuit for motor ST when, in due course of its cycle, the cam shaft would be rotated to open cam contact B1-B2 and close cam contacts B2-B3. With 40 contact 57 of relay IL closed, an energizing circuit as previously described, would maintain power to energize motor ST through a circuit as previously described so that rotation of the cam shaft would not be halted in its rest position R1 but would continue in its cycle, pass 45 through the rest position R1, open the cam contacts B2-B3 and close cam contacts B1 and B2.

As heretofore described, rotation of the cam shaft 50 would close cam contacts D1-D2 to complete the energizing circuit for relay G through a circuit from A.C. input line 15, through line 18, cam contacts D1-D2, line 21, the coil of relay G, line 22, line 10' to ground line 10.

55 Relay IL would be maintained energized through a lock-in circuit through its own contact 53, as previously explained and, as previously described, relay IGR would be energized.

Identical actions and reactions within the system of the lane changer occur as were previously described with reference to obtaining use of center lane L2 for inbound 60 traffic. The motor ST would continue to rotate the cam shaft until cam contacts A2-A3 open and A1-A2 close at which point motor ST would stop. The stop or rest position is indicated on the cam shaft chart as position R2.

65 Power would have been applied to the output lines MIG, MCL and GI of the master lane changer MLC, as previously described, with an effect similar to that described above upon the relays of the local lane changer, FIG. 3, and the relay of the detector selector, FIG. 4.

70 The transition from use of center lane L2 by inbound traffic to use of center lane L2 by outbound traffic through a substantial change in relationship between inbound and outbound traffic would be similar to the transition described from outbound traffic use of center lane L2 to

inbound traffic use of center lane L2 in that the motor ST would not come to rest in position R1 but would continue revolving the cam shaft to complete one full revolution from rest position R2 through a cycle to again come to rest in position R2.

With use of center lane L2 accorded to inbound traffic the relays IL and IR would be energized in the master lane changer, FIG. 2, while the relays OL and OR would be deenergized.

Detectors ID and IDD actuated by inbound traffic would be included in the counting or sampling of the inbound traffic flow while detector OD would be included in the counting or sampling of the outbound traffic flow.

To effect a complete transition the relay OR would become energized and relay IR would become deenergized.

With the cam shaft of the master lane changer of FIG. 2 on its rest position R2, deenergized relay IR would close its contacts, including contact 52.

Closure of contact 52 completes a circuit for the A.C. input through lines 15 and 18, contact 54/55, contact 52, line 88, cam contact A1-A2, motor ST, line 25 to ground line 10.

The motor ST will advance the cam shaft in its cycle toward position R1, while the signals will change from inbound green to inbound yellow to inbound red, as previously described, while the outbound red signal holds. During the transition when the line GI becomes deenergized the detector IDD is withdrawn from the inbound traffic counting or sampling system. The cam shaft having reached position R1 does not stop but continues toward position R2 to complete the transition. The outbound red signal changes to outbound green while the inbound red signal holds, as fully described above.

When the use of the center lane is accorded to outbound traffic the detector ODD is included in the counting or sampling system of the outbound traffic, along with detector OD.

If the traffic flows remain unbalanced in favor of outbound traffic use of the center lane will remain with the outbound traffic flow.

It should be noted that should both relays IGL and OGL in FIG. 3 become energized at the same time, for any reason, a circuit is completed to illuminate both inbound red signal IRS and outbound red signal ORS. Signal IRS is illuminated via a circuit from the A.C. input line 110 through line 84, contact 102/102, contact 111/112, switch SW1, line 85, signal IRS to ground 100. Signal ORS is illuminated via a circuit from the A.C. input line 110 through 86, contact 114/115, contact 104/105, switch SW2, line 87, signal ORS to ground 100.

The inbound green or yellow signals and the outbound green or yellow signals would be extinguished by the opening of contacts 112/113 and 105/106 respectively.

Description of detector selector circuit of FIG. 5

FIG. 5 illustrates, in circuit form, another form of detector selector utilizing a single detector CD in lane L2 which would serve as a common detector to count both inbound or outbound traffic in center lane L2 instead of two detectors IDD and ODD in center lane L2, as seen in FIG. 4.

The input lines IDL and ODL from the cycle selectors ICS and OCS are comparable to the similarly lettered input lines in FIG. 4.

The input lines GI and GO as seen in FIG. 5 are comparable to the similarly lettered input lines GI and GO in FIG. 4 and serve similar purposes.

The circuit for input power through IDL or ODL to the detector CD is controlled by the relays SDI and SDO respectively, which relays are energized via the input lines GI and GO respectively.

When input line GI is energized from the master lane changer, during the time the inbound green signal is illuminated, the relay SDI would be energized through a

circuit from the input line GI through the coil of relay SDI, line 168, line 167 to ground line 166.

Relay SDI would close its contact DS11 to complete a circuit to apply power from input line IDL through contact DS11 of relay SDI, contact DS12/DS13 of relay SDO to the detector unit CD to line 165 to ground line 166.

The completion of this detector circuit, with power applied from the inbound cycle selector ICS through the input line IDL, would make the detector CD in center lane L2 part of the inbound traffic counting system.

When the input line GI is deenergized, the inbound traffic detector circuit would be broken at contact DS11 from input line IDL.

When the input line GO is energized, the relay SDO would be energized through a circuit formed by the input line GO, the coil of relay SDO, line 167 to ground line 166.

Energized relay SDO would close its contact DS13/DS14 and complete a circuit to apply power from the outbound cycle selector OCS through line ODL, contact DS13/DS14 to detector CD to line 165 to ground line 166.

Completion of the outbound input line ODL to the detector CD in the center lane L2 would make the detector CD part of the outbound traffic counting system.

With both relays SDI and SDO deenergized, no power is applied to the detector CD so that the detector will not be in either the inbound or the outbound traffic counting system.

Description of self-selecting detector circuit of FIG. 8

A third method of detecting or counting either inbound or outbound traffic in center lane L2 is also offered herein. FIG. 8 illustrates a circuit diagram of the self-selecting detector selector which device may be used with a bi-directional detector BD for example. The bi-directional detector BD is illustrated with a common ground plate GP with two contact plates PI and PO.

The bi-directional detector BD is also designed that the contact plates PI and PO will make contact with the ground plate GP in sequence, either PI then PO, or PO then PI as a vehicle crosses over the detector, depending on the direction of travel of the vehicle.

When the self-selecting detector selector is used to detect traffic in center lane L2, for example, a single bi-directional detector of the type illustrated would be placed in center lane L2.

Let it be assumed that use of center lane L2 has been granted to inbound traffic. The inbound vehicles in the center lane would cross over the bi-directional detector BD so that the plate PI would be compressed to make contact with the ground plate GP and then, rolling the wheels of the vehicle forward, the plate PO would be compressed to make contact with the ground plate GP so that before contact of plate PI to ground plate GP is broken plate PO would make contact with the ground plate GP.

As contact is made between plate PI and ground plate GP, a circuit would be completed from the A.C. input line 170 through the coil of relay IDR, point 177, line 176, contact DS20/DS21 to plate PI, to plate GP, to line 171 to ground line 175 here considered to be a common ground.

Relay IDR thus energized would attract and close its contact DS25/DS26 and DS27. The wheel of the vehicle would roll forward and compress plate PO to make contact with the plate GP completing a second circuit before plate PI breaks its contact with plate GP. The second circuit is completed from the A.C. input line 170 through the coil of relay IDR, point 177, contact DS25/DS26, plate PO to plate GP, line 171 to the ground line 175.

The wheel of the vehicle would roll over and off the plate PI but would still maintain pressure on plate PO. The closure of contact DS27 of the relay IDR would com-

plete a circuit from the output line IDL from the cycle selector ICS to line 174 to ground line 175.

As the wheel of the vehicle would pass over and off the bi-directional detector BD, the plate PO would break contact with the ground plate GP, breaking the holding circuit for relay IDR which would in turn open its contacts DS25/DS26 and DS27.

The action would be obtained each time a wheel of a vehicle crosses the bi-directional detector in that direction so that the plate PI would be first compressed followed by the compression of plate PO.

Assume now that a vehicle crosses the bi-directional detector from the opposite direction for example an outbound vehicle in the center lane L2.

The wheel of the vehicle would first compress plate PO to make contact with the ground plate GP to complete a circuit to energize relay ODR from the A.C. input 170, through the coil of relay ODR, point 179, line 178, contacts DS24/DS25 of relay IDR to plate PO, ground plate GP, line 171 to ground line 175.

Relay ODR would close its contacts DS21/DS22 and DS23. When the wheel of the moving vehicle would compress plate PI to contact the ground plate GP, a circuit would be completed from the A.C. input line 170 through the coil of relay ODR, point 179, contact DS21/DS22 to the plate PI, the ground plate GP to line 171 to ground line 175. The circuit through plate PI would be completed before the circuit through plate PO would be broken by the release of the plate PO by the wheel of the vehicle as it crosses the bi-directional detector.

The closure of contact DS23 or relay ODR would complete the output circuit from the outbound cycle selector OCS through line ODL, contact DS23 of the relay ODR, line 173 to line 174, to ground line 175.

As the wheel of the vehicle would cross over and off the bi-directional detector BD, the plate PI would be released to break the holding circuit for the relay ODR which would then release its contacts DS21/DS22 and DS23.

The opening of contact DS23 would break the output circuit from the outbound cycle selector OCS through line ODL.

It should be noted that the description above includes overlapping of the contact closures of the plates of the bi-directional detector. If the contact plates are sufficiently far apart so that there would be no overlapping of the contact closures the relays associated with the contact plates, such as ODR and IDR for example, may each be made a delayed action relay with the delay on release. Such delayed action relays would produce the same effect as overlapping contact closures.

Description of alternate form of lane changer of FIG. 7

FIG. 7 illustrates, in circuit form, an alternate form of lane changer which is a combination of the master lane changer, illustrated in FIG. 2 and the local lane changer, illustrated in FIG. 3.

It will be noted that FIG. 2 includes a broken horizontal line H1 across the circuit diagram just below the relay OGR and IGR. FIG. 7 has a similar broken horizontal line H1 across the diagram above the circuits with relays OGR, IGR and CL illustrated in phantom form above broken line H1. The broken line H1 in FIG. 2 and 7 are identical and serve to divide the FIG. 2 and identify such division in FIG. 7.

FIG. 7 shows that part of the circuit of the lane changer that would appear below the broken horizontal line H1 in FIG. 2. The entire circuit of the alternate form of lane changer is not presented in FIG. 7 because that part of the circuit of the lane changer that is not shown in FIG. 7 is identical with the circuit above the broken horizontal line, H1 seen in FIG. 2.

The relays OGR, IGR and CL, illustrated in phantom form in FIG. 7, are identical with the identically lettered relays illustrated in FIG. 2.

The relay CL would control the contacts 157/158, 158/159, 161/162 and 162/163 in FIG. 7 while the relay OGR would control contacts 151/152, 152/153, 154/155 and 155/156 in FIG. 7 and relay IGR would control contacts 141/142, 142/143, 144/145 and 145/146 in FIG. 7.

The relays CL, OGR and IGR would be energized through their respective circuits, as appear in FIG. 2, from the A.C. input line 15 similarly numbered with the 10 A.C. input line in FIG. 7.

The signal lights ORS, OYS, OGS, IRS, IYS, and IGS would be illuminated via circuits from the A.C. input 15, through the contacts as controlled by the relays CL, OGR and IGR to the signals to be illuminated, to common ground line 10.

The signal lights are similar to the signals heretofore described and are used to control directional vehicle travel in center lane L2 as previously described.

The lane changer, as distinguished from the master 20 lane changer, directly controls the signals for control of the center lane L2 without the necessity of utilizing the local lane changer as illustrated in FIG. 3.

The output lines GO and GI would be energized from points 185 for line GO and 186 for line GI.

Description of lane changing system of FIG. 6

Let us assume that an entire lane changing system is composed of the devices as shown in the block diagram, FIG. 6, controlling a roadway RY composed of three 30 lanes, L1, L2 and L3, with center lane L2 the subject of reversible control.

The system disclosed in FIG. 6 utilizes a bi-directional detector BD in lane L2 connected to a self-selecting detector selector BDS illustrated in FIG. 8. This eliminates 35 the necessity of using output lines GI and GO.

The inbound detector ID on lane L1 and outbound detector OD in lane L3, connected to their respective inbound and outbound cycle selectors ICS and OCS, effectively count the inbound traffic in lane L1 and the outbound traffic in lane L3 during the traffic sampling time periods. The output circuits of the cycle selectors that are connected to the system selector MC serve identical purposes as previously described.

Inbound and outbound traffic in center lane L2 is counted through appropriate actuations of the bi-directional detector BD, as previously explained with reference to FIG. 8, via the output line IDL and ODL of the 40 inbound and outbound cycle selectors.

The output lines IG and OG of the system selector MC are energized as previously explained according to the determination of the system selector MC as selected by the relative cycle positions of the cycle selectors.

When there is a relative difference, for example, of 45 two or more cycle positions as selected by the cycle selectors, the system selector will energize and/or deenergize the appropriate output lines IG or OG, as previously described.

The action within the circuits of the lane changer LC above broken line H1 would be identical to the action 60 of the circuits in FIG. 2 above broken line H1, as previously described. However, where in FIG. 2, the several relays of the master lane changer close contacts to energize output lines to the local lane changer LLC, the lane changer LC, in FIG. 7 closes its own relay contacts to directly illuminate the control signals.

In a manner similar to that previously described, the combination of energizing and deenergizing the relays CL, OGR and IGR would control their respective contacts to illuminate the appropriate signals.

When the relays CL, OGR and IGR are all energized or all deenergized red signals ORS and IRS are illuminated one signal for each traffic flow thereby denying use of center lane L2 to both inbound and outbound traffic and maintaining center lane L2 as a buffer lane between 70 traffic in lanes L1 and L3.

When relay IGR alone is energized, a yellow inbound signal IYS is illuminated and a red inbound signal ORS is illuminated.

When relay OGR alone is energized, a yellow outbound OYS signal is illuminated and a red inbound signal IRS is illuminated.

The combination of relay IGR and CL being energized with relay OGR deenergized would produce the illumination of the green inbound signal IGS and the red outbound signal ORS while the combination of relay OGR and CL being energized with relay IGR deenergized would produce the illumination of the green outbound signal OGS and the red inbound signal IRS over the center lane L2.

The outbound red signal ORS may be illuminated by the A.C. input from line 15 through line 199, contact 152/153 of deenergized relay OGR, line 191, line 191', signal ORS to ground line 10, or from the A.C. input through line 15, line 190, contact 151/152 of energized relay OGR, contact 141/142 of energized relay IGR, line 191', signal ORS to ground line 10.

The outbound yellow signal may be illuminated by the A.C. input line 15 through line 199, contact 151/152 of energized relay OGR, contact 142/143 of deenergized relay IGR, line 192, contact 158/159 of deenergized relay CL, line 193, signal OYS to ground line 10.

The outbound green signal OGS may be illuminated by the A.C. input from line 15 through line 199, contact 151/152 of energized relay OGR, contact 142/143 of deenergized relay IGR, line 192, contact 157/158 of energized relay CL, to point 185, line 194 to signal OGS to ground line 10. When the green signal OGS is illuminated, the output line GO is energized from point 185.

The red inbound signal IRS may be illuminated from the A.C. input from line 15 through line 195 to contact 145/146 of deenergized relay IGR, line 196, line 196' to signal IRS to ground line 10, or from the A.C. input through line 15, line 195, contact 144/145 of energized relay IGR, contact 154/155 of energized relay OGR, to line 196', signal IRS to ground line 10.

The yellow inbound signal IYS may be illuminated from the A.C. input from line 15 through line 195, contact 144/145 of energized relay IGR, contact 155/156 of deenergized relay OGR, contact 162/163 of deenergized relay CL to line 197 to signal IYS to ground line 10.

The green inbound signal IGS may be illuminated from the A.C. input from line 15 through line 195, contact 144/145 to energized relay IGR, contact 155/156 of deenergized relay OGR, contact 161/162 of energized relay CL to point 186, line 198 to signal IGS to the ground line 10.

The output line GI of the lane changer would be energized through point 186 when the inbound green signal IGS would be illuminated.

In the description herein it is disclosed that when use of the reversible lane, L2, is accorded to one of the traffic flows, either inbound or outbound the relay IL or OL will be energized respectively.

If, due to a power failure and subsequent return of power or, failure of one of the relays to remain energized, as explained, or, if the relays should get out of synchronization with the cam shaft so that both relays IL and OL are deenergized when the cam shaft is in its position R2 or, both relays IL and OL are energized in the said position, a circuit is provided to energize motor ST to move the cam shaft from its rest position R2 so that the lane changer will synchronize itself internally.

Referring to FIG. 2, with both relays IL and OL deenergized a circuit is completed from the A.C. supply through line 15, line 18, contact 55/56, contact 39/40, line 88, cam contacts A1-A2, motor ST, line 25 to ground line 10.

If both relays should be energized a circuit is completed from the A.C. supply through line 15, line 18, con-

tact 55/54, contact 39/38, line 88, cam contacts A1-A2, motor ST, line 25 to ground line 10.

With relays IL and OL both energized or both deenergized red signals will be illuminated to both inbound and outbound traffic in center lane L2.

In the description above it was assumed that normally, during average or non-peak traffic periods, the center lane was used as a buffer lane or safety zone between the traffic flows on the lanes L1 and L3, each traffic flow being allocated one lane each.

Let it now be assumed that average or non-peak traffic is unbalanced so that normally one traffic flow, for example inbound, exceeds the average outbound traffic flow for example, so that during the average traffic periods and peak inbound traffic periods the inbound traffic is accorded use of one lane, L3.

Biassing the lane changing system by adjusting switches

It may be desired to bias the lane changing system so that pseudo-inbound peak traffic conditions appear during actual non-peak traffic conditions or so that pseudo-outbound peak traffic conditions appear during actual non-peak traffic conditions by adjustment of switch 200 or 210, as the case may be.

Reversible control over one of the center lanes of a four or six-lane roadway may lead to allocation of, in the case of a four-lane roadway, three lanes to inbound traffic and one lane to outbound traffic during inbound peak traffic conditions, for example, and two lanes allocated to inbound traffic and two lanes allocated to outbound traffic during outbound peak traffic conditions and non-peak traffic conditions for example. The reverse condition is also possible, that is three lanes allocated to outbound traffic and one allocated to inbound traffic during outbound peak traffic conditions and two lanes allocated to each traffic flow during inbound peak traffic conditions and non-peak traffic conditions.

Of course in either of the last mentioned cases allocation of the reversible lane to obtain equal distribution of the lanes of a four or six-lane road during non-peak traffic periods may be obtained by adjustment of the switches 200 and 210, as desired.

When adjustment of switches 200 and 210 is made to obtain a pseudo-peak traffic period, either inbound or outbound, during average or non-peak traffic periods the cam shaft does not come to a stop in the rest position R1 but is driven by the motor ST through a complete cycle from rest position R2 through position R1 back to position R2.

This condition may be obtained by making average traffic conditions appear as inbound peak traffic conditions in the lane changing system, thus producing pseudo-inbound peak traffic conditions during average traffic conditions.

Switches 200 and 210 are provided in the master lane change, as it appears in FIG. 2, to permit such variations.

By leaving switch 210 in contact with point 211, as it appears in FIG. 2 and adjusting switch 200 to make contact with point 202 the energizing circuit for relay OR is changed to include contact 204 of relay IR.

During average or non-peak traffic conditions, as explained more completely above, both of the input lines IG and OG are energized. With switch 210 in contact with point 211 the relay IR is energized from line IG through switch 210, points 211 and 216 to the relay IR.

With relay IR energized its contact 204 is open and even though line OG is energized the relay OR is deenergized because of open contact 204 in the energizing circuit of relay OR.

Thus during average or non-peak traffic conditions relay IR is energized and relay OR is deenergized thereby simulating inbound peak traffic conditions during normal traffic periods.

During actual inbound peak traffic conditions the input line IG is energized to energize relay IR but input line OG is deenergized. During actual outbound peak traffic

conditions the input line IG is deenergized and input line OG is energized to energized relay OR through switch 200, point 202, line 203, contact 204 of now deenergized relay IR, line 205, point 206 to relay OR, line 12 to ground line 10.

It may be desired to develop pseudo-outbound peak traffic conditions during average or non-peak traffic periods. This may be accomplished by adjusting switch 210 to make contact with point 212 and leave switch 200 in contact with point 201, as in FIG. 2.

With switches 200 and 210 adjusted to this position and both input lines IG and OG energized, the relay OR would be energized from the line OG through switch 200, point 201, point 206, relay OR, line 12 to ground 10.

With relay OR energized its contact 214 will be open so that the relay IR energizing circuit will be open at contact 214.

During outbound peak traffic conditions line IG will be deenergized and input line OG will be energized to energize relay OR alone.

During inbound peak traffic conditions the line IG will be energized and line OG will be deenergized therefore relay IR will be energized from the input line IG through switch 210, point 212, line 213, contact 214, line 215, point 216, relay IR, line 11 to ground line 10.

Description of plural lane reversing system of FIG. 9

Referring now to FIG. 9 a lane changing system for control of two adjacent interior traffic lanes of a four-lane roadway is represented in block diagrammatic form with each lane of the two adjacent interior traffic lanes individually controlled by a master lane changer with the master lane changers interconnected so as to provide cross control of the master lane changers between the master lane changers themselves.

Where it is practical, parts of FIG. 9 that are substantially similar to parts of the diagrams of FIG. 1, FIG. 2 and/or FIG. 6 are identically labeled.

At the top of FIG. 9 a multi-lane roadway RY is represented with lane L11 permanently allocated to inbound vehicle traffic and lane L44 permanently allocated to outbound vehicle traffic.

Associated with lane L11 is a vehicle detector ID for detecting vehicles traveling in lane L11. Upon actuation of the vehicle detector a detection pulse is applied to the inbound cycle selector ICS which, as previously explained, measures inbound vehicle traffic and, after a timed period, energizes one of the leads AI through FI as an output which corresponds to the measurement of traffic at the end of the time period and holds such lead energized until a change in the measurement of inbound vehicle traffic requires a change in output corresponding to such measurement.

Associated with lane L44 is a vehicle detector OD for detecting vehicles traveling in lane L44. Upon actuation of the vehicle detector a detection pulse is applied to the outbound cycle selector OCS which, being similar to ICS, measures outbound vehicle traffic and provides an output corresponding to the measurement obtained at the end of a similar or the same time period.

The lanes L22 and L33 may be allocated to inbound traffic or outbound traffic, according to the demand of vehicle traffic traversing the roadway RY. Each lane is individually controlled by signals represented by the signal lights labeled lane L22 and lane L33 at the bottom of the diagram.

Associated with lane L22 are two vehicle detectors ID1 and OD2, each vehicle detector being connected to detector selector, DS1 which detector selector is controlled, via leads GI1 and GO1, by the master lane changer MLC1.

When lane L22 is allocated to inbound vehicle traffic, detector selector DS1, which may be similar to the detector selector illustrated in FIG. 4, provides a complete circuit between vehicle detector ID1 and cycle selector ICS

and holds open the circuit between vehicle detector OD2 and cycle selector OCS. On the other hand when lane L22 is allocated to outbound vehicle traffic, detector selector DS1 provides a complete circuit between vehicle detector OD2 and cycle selector OCS and holds open the circuit between vehicle detector ID1 and cycle selector ICS.

Associated with lane L33 are two vehicle detectors ID2 and OD1, each detector being connected to detector selector DS2 which detector selector is controlled, via lead GI2 and GO2, by the master lane changer MLC2.

When lane L33 is allocated to outbound vehicle traffic detector selector DS2, which may be similar to detector selector DS1, provides a complete circuit between vehicle detector OD1 and cycle selector OCS and holds open the circuit between vehicle detector ID2 and cycle selector ICS. When lane L33 is allocated to inbound traffic detector selector DS2 provides a complete circuit between vehicle detector ID2 and cycle selector ICS and holds open the circuit between vehicle detector OD1 and cycle selector OCS.

Although FIG. 9 is presented with two vehicle detectors in each reversible lane and detector selectors similar to that illustrated in FIG. 4 an alternate combination of vehicle detector and detector selector may be used. As for example, in lieu of the two vehicle detectors ID1 and OD2, and detector selector DS1 associated with lane L22, one vehicle detector CD, as in FIG. 5, may be used in conjunction with the detector selector illustrated in FIG. 5 or one vehicle detector, BD, as in FIG. 8, may be used in conjunction with the self-selecting detector selector illustrated in FIG. 8. If the latter combination were to be employed in the lane changing system of FIG. 9 it would be unnecessary to provide the control leads GI1 and GO1 to the self-selecting detector selector.

Of course alternate forms of detector switching may be used in the lane L33 as well as in lane L22.

It should be noted that in FIG. 9 the vehicle detectors and their respective circuits to the cycle selector with which each is associated feed into a common input into the cycle selector where, as in FIGS. 1 and 6, multiple inputs to the cycle selector are represented. Obviously multiple vehicle detectors may be fed either individually to multiple input terminals or jointly to a common lead or terminal according to the design of the cycle selector or counting device.

The cycle selectors ICS and OCS each are represented as having six outputs each which are applied individually to a block MC, which may be a master controller, which compares the output, via leads AI through FI, of cycle selector ICS with the output via leads AO through FO, of cycle selector OCS and provides an output in the form of joint or several energization of the leads IG and OG.

The blocks ICS and OCS may be other devices which sense or measure one or another traffic characteristic, the output of which may be a voltage proportional to such measurement or count, or the blocks ICS and OCS may be various ration devices which may provide the type of output for operation of the block MC.

The blocks labeled MLC1 and MLC2 individually represent master lane changers and may be similar to the master lane changer of FIG. 2 for example.

It will be noticed that master lane changer MLC1 has switch 210 adjusted to contact terminal 211 and switch 200 adjusted to contact terminal 202. This provides that during average or balanced traffic conditions when the master controller, MC, is energizing both output lines IG and OG the master lane changer MLC1 will respond as if a call for peak inbound traffic conditions had been received. This is referred to above as the development of pseudo peak traffic conditions during average or balanced traffic conditions. Thus, during balanced traffic conditions, as here assumed, pseudo inbound peak traffic conditions are developed in the master lane changer

MLC1 by the setting of the switches 200 and 210 and the lane L22 is allocated to the inbound traffic flow during such balanced traffic conditions.

It will also be noticed that master lane changer MLC2 as its switch 210 adjusted to contact terminal 212 and its switch 200 adjusted to contact terminal 201. This provides that during average or balanced traffic conditions the master lane changer MLC2 will respond as if a call for peak outbound traffic conditions had been received. Thus, during balanced traffic conditions pseudo outbound peak traffic conditions are developed in the master lane changer MLC2 by the setting of its switches 200 and 210 and the lane L33 is allocated to the outbound traffic flow during such balanced traffic conditions.

Also, illustrated in the master lane changers MLC1 and MLC2 are the cam contacts E1, E2, and E3 with cam contacts E2-E3 closed and cam contacts E1-E2 open. This, referring to the cam chart at the bottom of FIG. 2, indicates that the master lane changers may be in the rest period R2.

Accordingly the relay MIGR is illustrated energized indicating that output lead MIG1 is energized by MLC1 and the relay MOGR is illustrated energized indicating that output lead MOG2 is energized by MLC2. Thus with the respective relays energized the respective contacts 219 and 217 are closed. Closure of contact 217 provides a circuit from the upper terminal of switch 10 through lead 221, contact 217, lead 222 to cam contact E2 of master lane changer MLC2 and with cam contacts E2-E3 closed, completes the input circuit via lead G1 to lead IG from the master controller.

Thus with master lane changer MLC2 in outbound peak traffic conditions, i.e. leads MOG2 and MLC2 energized and its cam shaft in, or almost in the rest period R2, as indicated by closure of cam contacts E2-E3, the input into switch 210 via lead IG may be either energized or deenergized according to the output of the master controller MC. The output lead OG from the master controller MC is applied directly to the upper terminal of switch 200 of master lane changer MLC1.

As previously stated, with the switches 200 and 210 of master lane changer MLC1 adjusted, as illustrated, inbound peak traffic conditions will be developed by the master lane changer MLC1 in the lane L22 when balanced traffic conditions (with both output leads IG and OG energized), are called for by the master controller MC, and inbound peak traffic conditions will be developed when inbound peak traffic conditions (lead IG energized and lead OG deenergized) are called for by the master controller MC and outbound peak traffic conditions will be developed in the lane L22 when outbound peak traffic conditions (lead OG energized and lead IG deenergized) are called for by the master controller MC.

With the switches 200 and 210 of master lane changer MLC2 adjusted as illustrated, outbound peak traffic conditions will be developed by the master lane changer MLC2 in the lane L33 in response to a call for balanced traffic conditions and in response to a call for outbound traffic conditions while inbound peak traffic conditions will be developed in the lane L33 in response to a call for inbound peak traffic conditions.

Thus with the master lane changer MLC2 in position 2 developing outbound peak traffic conditions in the lane L33 the master lane changer MLC1 is free to respond to a call for outbound peak traffic conditions from the master controller MC.

If the cam shaft of the master lane changer MLC2 were in a position other than almost in or in period R2 so that cam contacts E1-E2 were closed and E2-E3 were open then the lead 222 would be energized via power supplied through cam contact E1 so as to hold the master lane changer MLC1 in inbound peak traffic conditions by applying power to the switch 210 thus simu-

lating energization of lead IG, or, if the master lane changer MLC2 were in other than outbound peak traffic conditions so that the output lead MOG2 were deenergized, then the relay MOGR would be deenergized and contact 218 of relay MOGR would be closed and would supply power to the switch 210 also simulating energization of lead IG, holding the master lane changer MLC1 in inbound peak traffic conditions.

Thus it may be seen that the master lane changer MLC1 may develop outbound peak traffic conditions only in response to a call for outbound peak traffic conditions by the master controller MC and only when the master lane changer MLC2 is in or about to go into the period R2 of the cam shaft cycle while developing outbound peak traffic conditions. This provides that outbound peak traffic condition signals may be displayed over lane L22 only when outbound peak traffic condition signals are being displayed over the lane L33.

The upper terminal of switch 210 of MLC2 is connected directly to the output lead IG of master controller MC while the upper terminal of switch 200 of MLC2 is connected via lead 225, contact 219 of energized relay MIGR, lead 226 to cam contact E2 and, when cam contacts E2-E3 are closed, via lead OG2 to lead OG from the master controller MC.

The relay MIGR is illustrated energized thus indicating that lead MIG1 from MLC1 is energized, therefore contact 219 is illustrated closed. With the last described circuit complete the master controller MLC2 is free to respond to a call from the master controller MC for inbound peak traffic conditions.

The master lane changer MLC1 is represented with its cam shaft in or almost in the period R2 as indicated by the closure of cam contacts E2-E3 and with the output lead MIG1 energized, as indicated by the energization of relay MIGR, the block MLC1 is developing inbound peak traffic conditions.

If the master lane changer MLC1 had its cam contacts E2-E3 open and E1-E2 closed positive power through cam contact E1 would be supplied via cam contact E2, lead 226, contact 219, lead 225 to the upper terminal of switch 200 of MLC2 to simulate energization of lead OG and hold the master lane changer MLC2 in inbound peak traffic conditions. If the master lane changer MLC1 were in a condition other than inbound peak traffic conditions the output lead MIG1 of MLC1 would be deenergized and the relay MIGR would be deenergized thus its contact 220 would be closed to supply power through contact 220 and lead 225 to the upper terminal of switch 200 of MLC2 thus simulating energization of the lead OG from the master controller MC.

Thus it may be seen that the master lane changer MLC2, having developed outbound peak traffic conditions and arriving in the period R2 cannot thereafter move out of such condition unless three contingencies exist, i.e., a demand for inbound peak traffic conditions by the master controller, the master lane changer MLC1 is in or about to go into period R2 and the master lane changer MLC1 is developing inbound peak traffic conditions.

It may also be seen that the master lane changer MLC1, having developed inbound peak traffic conditions and arriving in the period R2 cannot thereafter move out of such condition unless three contingencies exist, i.e., a demand for outbound peak traffic conditions by the master controller, the master lane changer MLC2 is in or about to go into period R2 and the master lane changer MLC2 is developing outbound peak traffic conditions.

The operation of a master lane changer, in response to the output of the master controller MC via leads IG and OG has been described relative to FIG. 2 and the use of the switch 200 and 210 have also been described.

The master lane changers MLC1 and MLC2 may be similar to and may operate similar to the master lane changer of FIG. 2. However, the input from MC via lead IG to MLC1 in FIG. 9 is fed through cam contact

E2-E3 of MLC2 and to a contact controlled by a relay, the relay being controlled by the output of MLC2. A similar interconnecting circuit arrangement between the input from MC via lead OG to MLC2 is provided, with the lead OG being fed through cam contact E2-E3 of MLC1 and to a contact controlled by a relay, the relay being controlled by the output of MLC1.

Assumed initial conditions of operation of lane changing system of FIG. 9

Let it now be assumed that the lane changing system represented in FIG. 9 is operating so as to control the direction of traffic flow in lanes L22 and L33; that the vehicle detectors ID and ID1 are being actuated by inbound traffic in the lanes L11 and L22 respectively and the impulses are being applied to inbound cycle selector ICS; that the vehicle detectors OD and OD1 are being actuated by outbound traffic in the lanes L44 and L33 respectively and the impulses are being applied to outbound cycle selector OCS; that the inbound cycle selector ICS and outbound cycle selector OCS are energizing corresponding steps or cycles, as for example CI and CO respectively; that the master controller MC is calling for normal or balanced traffic conditions by energizing leads IG and OG; that because of the setting of switches 200 and 210 of MLC1 the master lane changer MLC1 is developing inbound traffic conditions in lane L22 via energization of output leads MIG1 and MCL1; that the lead GI1 is energized so that DS1 connects vehicle detector ID1 to ICS and holds open the circuit between OD2 and OCS; that relay MIGR is energized and the cam shaft of MLC1 is at rest in period R2; that because of the setting of switches 200 and 210 of MLC2 the master lane changer MLC2 is developing outbound traffic conditions in lane L33 via energization of output leads MOG2 and MCL2; that the lead GO2 is energized so that DS2 connects vehicle detector OD1 to OCS and holds open the circuit between ID2 and ICS and, that the relay MOGR is energized and the cam shaft of MLC2 is at rest in period R2.

In this assumed condition two lanes L11 and L22 are allocated to inbound traffic and two lanes L33 and L44 are allocated to outbound traffic.

Operation of master lane changers MLC1 and MLC2 of FIG. 9—assuming traffic conditions change from substantially balanced inbound and outbound to heavier inbound

Let it now be assumed that the volume of inbound vehicle traffic increases so that after subsequent sampling time periods the inbound cycle selector ICS energizes the output lead EI and that the volume of outbound vehicle traffic remains substantially the same so that the outbound cycle selector OCS maintains its output lead CO energized.

Under such conditions the master controller MC will determine the relationship between the two outputs and will set up a demand for peak inbound traffic conditions since the inbound vehicle traffic flow is numerically superior as between the two traffic flows. The call for peak inbound traffic conditions is made by maintaining the output lead IG energized and deenergizing the output lead OG.

Since the master lane changer MLC1 is developing inbound traffic conditions in the lane L22 the master lane changer MLC1 is unaffected by such change of demand from balanced traffic conditions to inbound peak traffic conditions. However the master lane changer MLC2 is developing outbound traffic conditions in lane L33 and the change of demand does effect the master lane changer MLC2.

When the master controller deenergizes the output lead OG the circuit between the output lead OG and the upper terminal of switch 200 of MLC2 via lead OG2 cam contacts E2-E3 of MLC1, lead 226, contact 219 and lead

225 become deenergized so that only the lead IG to the upper terminal of switch 210 of MLC2 is energized.

Thus the master lane changer MLC1 remains developing inbound traffic conditions and the master lane changer MLC2 responds to the demand of the master controller MC for peak inbound traffic conditions and starts its cam shaft rotating. When the cam shaft of MLC2 moves out of the period R2 its cam contacts E2-E3 open and its cam contact E1-E2 close. This holds the circuit between cam contact E2 of MLC2 and the upper terminal of switch 210 of MLC1 energized.

The advance of the cam shaft of MLC2 causes a change in the output in that lead MCL2 is deenergized while lead MOG2 is held energized. This causes a change in the signal indication over lane L33 so that the green signal having been displayed to inbound vehicle traffic in that lane is changed to a yellow signal while the red signal, displayed to outbound vehicle traffic over the lane L33 is maintained. With the subsequent deenergization of output lead MOG2 the relay MOGR becomes deenergized and its contact 217 is opened and its contact 218 is closed. This holds power on the upper terminal of switch 210 of MLC1 and simulates the energization of lead IG to MLC1. Also with lead MOG2 deenergized lead GO2 is deenergized and detector selector DS2 opens the circuit between vehicle detector OD1 and outbound cycle selector OCS while maintaining the open circuit between ID2 and ICS.

As the cam shaft of MLC2 advanced and the lead MOG2 was deenergized the yellow signal displayed to outbound traffic over lane L33 was changed to a red signal while the red signal displayed to inbound traffic was maintained. The cam shaft passes through period R1 without coming to rest and continues through the cycle of rotation all as previously described relative to FIG. 2 above. When the all red interval of the signal sequence terminates a red signal is held displayed over lane L33 to outbound vehicle traffic and a green signal is now displayed to inbound vehicle traffic over lane L33 as by the output leads MIG2 and MCL2 being energized. When the lead MIG2 is energized the lead GI2 is energized and the detector selector DS2 provides a circuit between vehicle detector ID2 and inbound cycle selector ICS and holds open the circuit between vehicle detector OD1 and outbound cycle selector OCS so that the vehicle pulses of ID2 will be applied to cycle selector ICS.

When the cam shaft MLC2 comes to position R2 it may come to rest. The cam contact E2-E3 close but the circuit to switch 210 of MLC1 is open at contact 217. Thus the lanes L11, L22 and L33 are now allocated to inbound traffic and lane L44 is alone allocated to outbound traffic.

This condition will hold so long as the master controller MC maintains its call for inbound peak traffic conditions.

Operation of master lane changers MLC1 and MLC2 of FIG. 9—assuming traffic conditions change from heavier inbound to substantially balanced

Assume now that after a period of time traffic conditions alter so that the traffic flows become substantially balanced and the cycle selectors energize corresponding output leads. The master controller MC will set up a demand for balanced traffic conditions by energizing output lead OG and maintaining output lead IG energized. The master lane changer MLC1 will remain unaffected since it is adjusted to develop inbound traffic conditions in response to a demand for normal or balanced traffic conditions by the master controller and it is now developing inbound traffic conditions. However, master lane changer MLC2 will respond to the demand for balanced traffic conditions by returning to the development of outbound traffic conditions.

The cam shaft of MLC2 will advance out of the R2 period and change certain of its cam contacts as for example, E2-E3 open and E1-E2 closed. The output lead

MCL2 will be deenergized resulting in a change of signal indication over lane L33 so that the green signal displayed to inbound traffic is extinguished and a yellow signal is illuminated while the red signal over lane L33, displayed to outbound vehicle traffic, is maintained. At termination of the clearance interval, the output MIG2 is deenergized thus deenergizing lead GO2 and causing DS2 to open the circuit between ID2 and ICS and causing the yellow signal over lane L33 to be extinguished and a red signal to be illuminated so that red signals are displayed to both directions over lane 33.

The cam shaft of master lane changer MLC2 passes through period R1 without stopping or coming to rest and proceeds toward period R2. When the all red interval terminates, a green signal is illuminated over lane L33 to outbound vehicle traffic and the red signal to inbound traffic is held. Simultaneously energization of the output lead MOG2 causes the relay MOGR to become energized and contacts 218 opens and 217 closes. However power is maintained to the upper terminal of switch 210 of MLC1 since cam contact E1-E2 are closed. The lead GO2 is energized to cause DS2 to close the circuit between OD1 and OCS. When the cam shaft reaches period R2 it may come to rest with its cam contacts E1-E2 open and E2-E3 closed so as to permit direct control of the master lane changer MLC1 by the master controller MC.

Operation of master lane changers MLC1 and MLC2 of FIG. 9—assuming traffic conditions change from heavier inbound to heavier outbound

Let it now be assumed that the lane changing system is in its previous condition, that is, both master lane changers are developing inbound peak traffic conditions with signals in both lanes displaying green signals to inbound traffic and red signals to outbound traffic, and instead of traffic altering so as to require balanced or average traffic conditions a complete reversal of relation between the traffic flows occurs so that the outbound traffic flow becomes substantially greater than the inbound traffic flow and with both master lane changers developing inbound traffic conditions in the lanes L22 and L33, a demand for outbound peak traffic conditions is made by the master controller MC by energizing its output OG and deenergizing its output IG.

Since cam contacts E2-E3 of MCL1 are closed and relay MIGR is energized, as by the energized output MIG1, the master lane changer MLC2 is under full control of the master controller MC. On the other hand with master lane changer MLC2 developing inbound traffic conditions the relay MOGR is deenergized due to the deenergization of lead MOG2. This holds the master lane changer MLC1 in inbound traffic conditions.

Thus with a demand for outbound peak traffic condition the master lane changer MLC2 responds and proceeds to advance through its cycle as previously described, to develop outbound peak traffic conditions while master lane changer MLC1 is held in inbound peak traffic conditions.

When the master lane changer MLC2 energizes its output lead MOG2 the relay MOGR becomes energized to open contact 218 and close contact 217 and when the cam shaft is about to go into rest period R2 so that the cam contacts E2-E3 close the circuit between the upper terminal of switch 210 of MLC1 and output lead IG of the master controller MC becomes deenergized so that the master lane changer MLC1 may respond to the call for outbound peak traffic conditions from the master controller MC.

The cam shaft of the master lane changer MLC1 now advances out of rest period R2 and its cam contacts E2-E3 open and E1-E2 close providing power via lead 226, contact 219 and lead 225 to the upper terminal of switch 200 of MLC2 simulating energization of the output OG of MC. The cam shaft of MLC1 continues to advance and output lead MCL1 becomes deenergized

and the green signal over lane L22 displayed to inbound vehicle traffic is extinguished and a yellow signal is illuminated while the red signal over lane L22 displayed to outbound traffic is maintained.

5 At termination of the clearance interval the output lead MIG1 is deenergized thus deenergizing relay MIGR and lead GI1 and extinguishing the yellow signal and illuminating a red signal displayed to inbound traffic over lane L22 as previously described.

10 Deenergization of relay MIGR closes its contact 220 and opens its contact 219, thus providing power via contact 220 and lead 225 to the upper terminal of switch 200 of MLC2 simulating energization of output OG of MC.

15 Deenergization of lead GI1 causes detector selector DS1 to open the circuit between vehicle detector ID1 and cycle selector ICS.

Rotation of the cam shaft of MLC1 continues and passes through the R1 period without stopping or coming to rest.

20 Termination of the all red interval occurs and output lead MOG1 is energized. This provides a green signal over lane L22 displayed to outbound vehicle traffic and maintains a red signal over lane L22 displayed to inbound vehicle traffic. In period R2 the cam shaft of MLC1 may come to rest, also the cam contacts E1-E2 open and cam contact E2-E3 close but the circuit to switch 200 of MLC2 is open at contact 219, while contact 220 is closed keeping power on switch 200 of MLC2 via lead 225.

25 Thus the lanes L44, L33 and L22 are allocated to outbound vehicle traffic and lane L11 is allocated to inbound traffic.

When the output lead MOG1 was energized the lead 30 GO1 became energized and caused detector selector DS1 to close the circuit between vehicle detector OD2 and cycle selector OCS and hold open the circuit between vehicle detector ID1 and cycle selector ICS.

35 With the master lane changers both developing outbound traffic conditions, the master lane changer MLC1 may respond to a change of demand by the master controller MC as the master lane changer MLC1 is now under direct control of the master controller MC. The master lane changer MLC2 is not now under direct control of the master controller due to deenergization of relay MIGR by the master lane changer MLC1 and the master lane changer MLC2 cannot now respond to a change of demand by the master controller until master lane changer MLC1 advances out of outbound traffic conditions and develops inbound traffic conditions and is in or is about to go into rest period R2.

40 Thus a demand by the master controller MC, for balanced traffic conditions, would cause MLC1 to advance its cam shaft resulting in the opening of cam contacts E2-E3 and closure of cam contacts E1-E2 and 45 in the deenergization of output lead MCL1 and the extinguishing of the green signal displayed to outbound traffic over lane L22 and illumination of a yellow signal while retaining the red signal displayed to inbound traffic in lane L22.

50 55 60 Subsequent deenergization of output lead MOG1 results in deenergization of lead GO1 which causes detector selector DS1 to open the circuit between OD2 and OCS and also results in a change of signal display so that red signals are displayed to both inbound and outbound traffic in lane L22. Master lane changer MLC1 passes through rest period R1 without stopping and advances toward period R2.

65 The output lead MIG1 is energized which results in energization of lead GI1 and relay MIGR and illumination of a green signal to inbound vehicle traffic over the lane L22 while the red signal display to outbound traffic over lane L22 is maintained. Energization of lead GI1 causes DS1 to complete the circuit between ID1 and ICS. Upon the opening of cam contact E1-E2 and closure of E2-E3 complete control over master lane changer MLC2

is returned to the master controller. When the cam shaft of the master lane changer MLC1 arrives in rest period R2 it may stop.

Thus the master lane changer MLC1 has returned to its normal rest condition, that is, developing inbound traffic conditions in lane L22 and the master lane changer MLC2 is in its normal rest condition, that is, developing outbound conditions in lane L33 with both master lane changers under complete control of the master controller.

Now each master lane changer is in a position to respond to the demand of the master controller when such demand is received and depending upon the demand, one of the master lane changers will respond all as previously described.

Description of master lane changer of FIG. 10

FIG. 10 illustrates in schematic circuit form, an alternate form of master lane changer or lane changing unit that may be represented in block form by block MLC in FIG. 1. This alternate form of master lane changer or lane changing unit may be associated in combination with other components to form a system as illustrated in FIG. 1, for example, with inbound and outbound cycle selectors, ICS and OCS which may be in the form of cycle selector as described in the said U.S. Patent 2,288,601, a master controller MC, which may be in the form of a system selector as described in the said U.S. Patent 2,542,978 and a signal control circuit or local lane changer LLC such as disclosed and described relative to FIG. 3, for example.

The lane changing unit of FIG. 10 includes two groups of line switch banks, arranged in 180-degree arc, each group including four banks with twenty-six contact positions on each bank; a timing assembly including a direct current supply, a potential divider PD+, timing resistors 251, 252, 253, 254, 255, 256 and 259, a timing capacitor 260, a gas diode 261 and a relay AS; two motor magnets MM1 and MM2; two preference selection relays IR and OR; two skip control relays AIR and AOR and three output control relays IGL, OGL and GY.

Motor magnet MM1 is associated with the step-by-step advancement of the wipers of the line switch banks LA1, LA2, LA3 and LA4, and motor magnet MM2 is associated with the step-by-step advancement of the wipers of the line switch banks LB1, LB2, LB3 and LB4.

One group of line switch banks LA1, LA2, LA3 and LA4 have four wiper blades for each bank with each wiper displaced 90 degrees. Each bank is so constructed as to encompass 180°, thus two sets of these blades will be making contact with each bank of each of these line switch banks at all times, making contact at two points, 13 positions apart. It will be understood by those skilled in the art that eight banks of line switches with 13 positions each may be substituted for the banks LA1, LA2, LA3 and LA4.

The group of line switch banks LB1, LB2, LB3 and LB4 each have two wiper contacts displaced from each other 180° with one wiper making contact with one of the 26 positions on its respective bank and as the one wiper advances from position 26 the second wiper advances to contact position 1.

Other means of opening and closing contacts in a sequential manner, such as by the use of a cam shaft and cam contacts, to provide the electrical equivalent of either one or both groups of line switches may be substituted for either one or both groups of line switch banks, as desired.

The timing capacitor 260 may be charged by a direct current supply, represented by a plus in a square, of the order of 450 volts, for example, through one of several circuits all passing through different positions of the line switch bank LA1 or through position 26 of bank LB1.

The relay AS is energized at the end of each timed interval. The motor magnets MM1 and MM2 are individually energized via closure of the contacts of relay AS in cooperation with the line switch banks.

The relays IR and OR of FIG. 10 control the lane changing unit and are themselves controlled via leads IG and OG respectively which leads are comparable to the identically labeled leads in FIG. 1 and FIG. 6.

5 It will be noted that the relays IR and OR in FIG. 2 are also controlled via two leads IG and OG respectively and that the master lane changer of FIG. 2 is controlled via energization and deenergization, in combination, of the relays IR and OR. Thus the relays IR and OR of 10 FIG. 10 compare with the identically labeled relays in FIG. 2.

The relays AIR and AOR provide means for skipping through certain positions of the line switch banks LA1, LA2, LA3 and LA4 when desired, as described below.

15 The relays in FIG. 10 are presented deenergized with all contacts in their normal condition with wiper contacts of banks LA1, LA2, LA3 and LA4 in positions 1 and 14 and of banks LB1, LB2, LB3 and LB4 in position 1. This is a rest condition of the lane changing unit and ordinarily 20 the relays IGL and OGL would both be energized.

The relays IGL, OGL and GY may be considered the signal control relays or output relays associated with the lane changing unit of FIG. 10.

If, for example, the local lane changer illustrated in 25 FIG. 3 were used to provide the desired signal indications over the reversible lane or lanes, and the leads 265', 266' and 300' were considered output leads then the leads 265', 266' and 300' of FIG. 10 may be considered connected to the leads MIG, MOG and MCL in FIG. 3 for 30 control of relays IGL, OGL and GY respectively of FIG. 3.

If, for example, the local lane changer illustrated in 35 FIG. 3 were used to provide the desired signal indications and the relay IGL, OGL and GY of FIG. 10 were considered output relays then the outputs from the contacts 360 of relay IGL, 361 of relay OGL and 362 of relay GY of FIG. 10 may provide power for energization of the signal control relays of FIG. 3 and output leads MIG, MOG and MCL in FIG. 10 may be considered as being 40 connected to the leads MIG, MOG and MCL respectively in FIG. 3.

Assumed initial conditions in operation of the master lane changer of FIG. 10

Let it be assumed for the purpose of the following description of the operation of the circuit in FIG. 10 that 45 normal traffic conditions have prevailed for a period of time long enough to permit all intervals to be timed out and that the lane changing unit is at rest with the wipers of line switch banks LA1, LA2, LA3 and LA4 in positions 1 and 14, and the wipers of line switch banks LB1, LB2, LB3 and LB4 in position 1 and relays IGL and OGL energized. It should also be assumed that the relays IR and OR are both energized via lead IG and OG.

Under the assumed conditions, indicator lamp 262 55 would be illuminated to indicate a rest condition. Lamp 262 is illuminated with the wiper of bank LA4 in positions 1 and 7 with a ground supplied via the wiper in position 1 and position 7 completing a circuit through lamp 262, contact 263 of relay AOR, contact 264 of relay 60 AIR to positive power represented by a plus in a circle hereinafter referred to as alternating current or A.C. The use of A.C. in the description is used as a convenience only, as any type of power may be substituted without altering the operation of the lane changing unit in any way.

Relay IGL would be energized via a circuit from A.C. through the coil of relay IGL, leads 265, position 1 of bank LA3 to ground. Relay OGL would be energized via a circuit from A.C. through the coil of relay OGL, lead 266, position 14 of bank LA3 to ground.

Let it also be assumed that the leads MIG, MOG and MCL of FIG. 10 are connected to the identically labeled leads of FIG. 3 so that when the outputs of FIG. 10, via MIG, MOG and MCL of FIG. 10, are energized the relay 75 IGL, OGL and GY of FIG. 3 are energized via the re-

spective leads. As previously described, relative to FIG. 3, energization and deenergization of the relays IGL, OGL and GY of FIG. 3 in combination provide illumination of certain signal lamps. The signal lamps that are illuminated and displayed to the traffic on the controlled roadway by the present combination shall be described below.

With the leads MIG and MOG energized, as by closure of contacts 360 and 361 respectively and lead MCL de-energized, as by open contact 362, the relays OGL and IGL in FIG. 3 are energized and relay GY of FIG. 3 is deenergized. With the switches SW1 and SW2 of FIG. 3 as illustrated, red signals would be displayed over the reversible lane to both directional traffic flows. If, however, the switches SW1 and SW2 were connected to terminals 107 and 108 respectively flashing yellow signals would be displayed over the reversible lane to both directional traffic flows.

It should be understood that the displaying to a traffic flow of a red signal, for example, over a lane would indicate to that traffic flow that use of the lane is prohibited to that traffic flow. The displaying to a traffic flow of a green signal, for example, over a lane would indicate to that traffic flow that use of the lane is permitted to that traffic flow. The flashing yellow signal would indicate dual use of the lane over which it is displayed so that the lane may be used for passing only and the steady yellow signal would indicate a potential change of signal display and thus the steady yellow signal would indicate a clearance of the lane.

Of course the presented signal indications are merely used for purposes of description and the use of other signal indications, as by other codes, arrows or signs, or otherwise, may be employed as desired.

Operation of master lane changer of FIG. 10—assuming traffic conditions change to cause system selector to call for inbound preference

Let it be assumed that traffic conditions on the roadway RY alter so as to cause the cycle selectors ICS and OCS to select and energize non-corresponding outputs or cycle positions and the system selector MC or master controller compares such energized cycle positions and accordingly calls for inbound traffic preference or conditions by maintaining lead IG energized causing lead OG to become deenergized which would maintain relay IR energized and cause relay OR to become deenergized.

The sequence of events desired is to change the all-red rest signal to a red signal to outbound and a yellow signal to inbound traffic or, if a flashing yellow signal is employed during the rest interval, to change the flashing yellow signal to a red signal to outbound vehicles and steady yellow signal to inbound vehicles and time a clearance interval before showing a green signal to inbound vehicle traffic while maintaining the red signal to outbound vehicles over the reversible lane.

The inbound preference will be called for when relay IR is energized and relay OR is deenergized. When relay OR dropped out and relay IR remained energized, a circuit became completed from the direct current supply hereinafter referred to as D.C., represented by a plus in a square through resistor 269, contact 270 of relay IR, contact 271 of relay OR, lead 272, position 1 of bank LA1, lead 273, lead 274 to capacitor to ground to rapidly charge capacitor 260 through low resistance 269. Capacitor 260 becomes charged to breakdown potential of the tube 261 and tube 261 passes current to energize relay AS. Relay AS closes its contacts 275 and 276. Closure of contact 275 provides an energizing circuit for motor magnet MM1 from A.C. through the coil of MM1, contact 275, lead 279, position 14 of bank LA2 to ground.

Upon energization of motor magnet MM1 the advancing mechanism (not shown) of the several wipers of the banks LA prepares to advance the wipers of the line switches LA1, LA2, LA3 and LA4 in unison to the next position. Upon energization, MM1 closes its contact 280

which contact is connected between the positively charged side of capacitor 260 and ground. Thus upon closure of contact 280 a discharge circuit is completed from the positively charged side of the capacitor through lead 274, resistor 277, contact 280, to ground and thus capacitor 260 is discharged to substantially ground potential and thus below the maintaining potential of tube 261 and tube 261 stops passing current thereby relay AS becomes deenergized and releases its contacts 275 and 276. Upon the opening of contact 275 motor magnet MM1 becomes deenergized, opens contact 280 and advances the wipers of the banks LA1, LA2, LA3 and LA4 to the next position.

With the wipers of the banks LA1, LA2, LA3 and LA4 in positions 2 and 15 on each bank the indicator lamp 262 is extinguished and indicator lamp 281 is illuminated indicating a clearance interval to inbound preference.

The clearance to inbound interval is now timed. The charging of the capacitor 260 is accomplished from the D.C. Supply through resistance of a potential divider, 20 between the D.C. and ground, indicated by PD+, through adjustable resistance 251, position 2 of bank LA1, lead 273, lead 274, to capacitor 260. When the capacitor is sufficiently charged the tube 261 passes current to energize relay AS and closure of contacts 275 and 276 results. Motor magnet MM1 does not now become energized because of the lack of a ground connection. However, motor magnet MM2, associated with line switch banks LB1, LB2, LB3, and LB4 does become energized via a circuit from A.C. through the coil of MM2, lead 282, contact 276, lead 283, 30 contact 284 of relay AIR, contact 285 of relay AOR, lead 286, lead 289, position 15 of bank LA2 to ground.

Energized motor magnet MM2 prepares to advance the wipers associated with line switch banks LB1, LB2, LB3 and LB4 and closes its contact 290 and opens its contact 35 291. Closure of contact 290 provides a ground connection to the positively charged side of capacitor 260 via lead 287, resistor 288, contact 290, lead 298 to bank LB4, position 1 to ground thus reducing the charge on the capacitor to substantially ground potential and thus below the maintaining potential of tube 261, thus deenergizing relay AS. Contacts 275 and 276 open dropping out MM2. When MM2 drops out contact 290 opens and the wipers of banks LB1, LB2, LB3 and LB4 are advanced in unison to the next position, position 2.

The line switch banks LA1, LA2, LA3 and LA4 remain with their wiper contacts on positions 2 and 15 since MM1 was not then energized. The capacitor 260 is again charged through the potential divider and adjustable resistance 251 and position 2 of bank LA1 and the motor magnet MM2 is again energized and thereafter de-energized, as previously described, only through position 2 of bank LB4 to advance the wipers of the line switch banks LB1, LB2, LB3 and LB4 to the next position.

This action is repeated until the wipers of the banks LB1, LB2, LB3 and LB4 are advanced step-by-step 55 25 positions into position 26. Thus the capacitor 260 is charged to the breakdown potential of tube 261 25 times thereby multiplying the time of the resistance-capacitance (RC) time constant associated with position 2 of bank LA1 25 times by the advance of the wipers of the line 60 switch banks LA remain in positions 2 and 15 during the 25-step transition. The interval thus timed is the clearance to inbound interval.

With the wipers of the LB series banks in position 26 and the wipers of the LA series banks in positions 2 and 65 15 the timing capacitor 260 is rapidly charged from the D.C. supply through the wiper of bank LB1, position 26 of bank LB1, resistance 292, lead 293 to the capacitor to ground. Relay AS is energized and contacts 275 and 276 close. Now both motor magnets MM1 and MM2 are 70 energized. MM1 is energized via a circuit from A.C. through coil MM1, contact 275, lead 279, lead 294, the wiper contact of bank LB2 in position 26, lead 295, lead 289 to position 15 of bank LA2 to the wiper contact to ground while MM2 is energized via a circuit previously traced.

Closure of contact 280 by the motor magnet MM1 provides a ground connection to reduce the charge on the timing capacitor 260 thus providing deenergization of relay AS and subsequently of the motor magnets MM1 and MM2 and advance of the wipers of the LA series of banks to positions 3 and 16 and of the wipers of the LB series of banks to position 1.

The indicator lamp 281 is extinguished and indicator lamp 296, the inbound minimum preference indication lamp, is illuminated.

In position 15 of bank LA3 the energizing circuit for relay OGL is open so that relay OGL drops out and closes its contact 299 and in position 16 of bank LA3 the relay GY is energized from A.C. through coil GY, lead 300, contact 299, lead 301 to position 16 of bank LA3 to the wiper to ground. With relay IGL energized and relays OGL and GY both deenergized, a red signal is displayed to outbound traffic and a yellow signal is displayed to inbound traffic in the reversible lane.

With the wipers of the LA series of banks in positions 3 and 16 the capacitor 260 is charged from D.C. through the potential divider, adjustable resistance 252 through the position 3 of bank LA1 and to the capacitor as previously described. Motor magnet MM1 is not energized because of a lack of ground connection while the motor magnet MM2 is energized all as previously described. The wipers of the LB series banks of line switches are advanced from position 1 through to position 26 as previously described and this advance charges capacitor 260 25 times as previously described, multiplying the time of the RC time constant associated with positions 3 of bank LA1 25 times to time the current interval.

The interval timed in positions 3 and 16 is the minimum inbound preference interval and indicator lamp 296, the minimum inbound preference indicator lamp, is illuminated.

The relays IGL and GY are both energized as relay IGL is maintained energized in positions 1 through 7 of bank LA3 and relay GY is energized in positions 16 and 17 of bank LA3. This relay combination provides a green signal over the reversible lane to inbound traffic and a red signal over the reversible lane to outbound traffic.

The wiper contacts of both groups of line switch banks LA and LB will advance together, the wipers of banks LA from positions 3 and 16 to positions 4 and 17 and the wipers of banks LB from position 26 to position 1.

The positions 4 and 17 of the banks LA are the inbound preference rest position and the lane changing unit may remain in this position so long as the relay IR remains energized and the relay OR remains deenergized. The relays IGL and GY are maintained energized as in position 16 and the green signals displayed to inbound traffic and the red signals displayed to outbound traffic over the reversible lane are maintained. This rest condition is maintained since the charging circuit for the capacitor 260 through position 4 of bank LA1 is open at contact 302 of relay IR and contact 303 of relay OR. In position 4 of bank LA4 the indicator lamp 306, the inbound rest indicator is illuminated.

Operation of master lane changer of FIG. 10—assuming traffic conditions change from heavier inbound to relatively balanced

Let it be assumed that traffic conditions change to relatively balanced flow so that the relay OR becomes energized and normal traffic conditions are called for. Energized relay OR will close its contact 303 thus completing a rapid charging circuit from the D.C. supply through resistance 269, contact 303, lead 304, lead 305, position 4 of bank LA1, the wiper contact, lead 273, lead 274 to capacitor 260.

The capacitor will rapidly charge to the breakdown potential of tube 261 and tube 261 will pass current to

energize relay AS. Motor magnet MM1 will become energized but motor magnet MM2 will remain deenergized since no ground is supplied to MM2 in position 17 of bank LA2.

5 Thus the wipers of the line switch banks LA are advanced to positions 5 and 18. In position 5 the lamp 307, the clearance from inbound preference indicator lamp, is illuminated and indicator lamp 306 is extinguished.

10 In position 18 of bank LA3 the relay GY is deenergized. This causes a signal change since only relay IGL of the three output relays is energized.

Positions 5 and 18 of the banks LA are clearance from inbound preference and the capacitor 260 is charged from the D.C., through part of the potential divider PD+, adjustable resistance 254, position 5 of bank LA1, lead 273, lead 274 to the capacitor 260. Upon operation of relay AS, as previously described, contact 275 and 276 close and motor magnet MM2 becomes energized and motor magnet MM1 remains deenergized. The wipers of the line switch banks LB are advanced step-by-step 25 times from position 1 to position 26 where a ground connection is provided for motor magnet MM1 and capacitor 260 is rapidly charged from D.C. through position 26 of bank LB1 and resistance 292 and both motor magnets MM1 and MM2 are energized and deenergized, as previously described, and the wipers of the banks LA are advanced to positions 6 and 19 while the wiper of banks LB are advanced off position 26 and onto position 1.

The clearance from inbound interval maintains a red signal over the reversible lane to outbound traffic and displays a yellow or clearance signal over the reversible lane to inbound traffic.

In position 6 of bank LA1 the capacitor 260 is charged from the D.C. through the potential divider PD+, adjustable resistance 253, lead 308, contact 309 of relay AOR, lead 310, position 6 of bank LA1, the wiper contact, lead 273, lead 274 to capacitor 260. Since a ground is supplied the motor magnet MM2 in position 19 of bank LA2 and ground is not now connected to MM1 the wipers of the banks LB will be advanced step-by-step 25 times from position 1 through to position 26 for multiplication of the time of the RC time constant. When the wipers of the banks LB are in position 26 the wipers of both groups of banks will advance together, the wipers of the banks LA to positions 7 and 20 and the wipers of the banks LB to position 1, as previously described.

50 In positions 19 and 20 of bank LA3, as well as in positions 21 through 26 inclusive, the relay OGL is energized. Thus in positions 6 and 19, and 7 and 20 the relays IGL and OGL are both energized. This relay combination may provide red signals over the reversible lane for both directions of traffic thereby excluding both directional traffic flows from the reversible lane, or may provide flashing yellow signals to traffic in both directions according to the setting of switches SW1 and SW2

55 60 in FIG. 3, with the latter signals providing dual use of the reversible lane, as for example as "passing lane only." In positions 6, 12 and 13 of bank LA4 the indicator lamp 311, the normal traffic minimum indicator lamp is illuminated and in position 7 of bank LA4 the lamp 262 is illuminated.

With the lane changing units in positions 7 and 20 of the banks LA and position 1 of the banks LB, normal rest positions, conditions similar to positions 1 and 14 of the banks LA and position 1 of the banks LB exist. The lane changing unit may rest in this condition until a change in the balance of traffic occurs and the cycle selectors select different and non-corresponding cycle positions.

Operation of master lane changer of FIG. 10—assuming traffic conditions change to warrant change from inbound preference to outbound preference

Let it now be assumed that traffic conditions alter sufficiently to warrant an outbound preference. This would be indicated by the relay IR becoming deenergized and relay OR remaining energized.

Closed contact 312 of relay OR and closure of contact 313 of now deenergized relay IR provides a rapid charging circuit via lead 272 through position 7 of bank LA1 resulting in energization of MM1 as previously described and the wipers of banks LA are advanced to positions 8 and 21 while the wipers of banks LB remain in position 1.

In position 8 of bank LA3 the ground connection for relay IGL is opened and the relay drops out, leaving relay OGL energized and IGL and GY deenergized. In position 8 of bank LA4 lamp 262 is extinguished and lamp 314, the clearance to outbound indicator, is illuminated. The position 8 of the bank LA1 times the clearance to outbound preference interval and since a ground is supplied to MM2 and not to MM1 at position 21 of bank LA2 the time of the RC time constant including the potential divider, adjustable resistance 255 associated with position 8 of bank LA1 and capacitor 260 will time out 25 times and again the wipers of both groups of banks will advance together from positions 8 to 21 to positions 9 and 22, and position 26 to position 1.

During the clearance to outbound interval a red signal is displayed to inbound traffic and a steady yellow signal displayed to outbound traffic over the reversible lane.

In positions 9 and 10 of bank LA3 the relay GY is energized via the contact 315 of relay IGL. In position 9 of bank LA4 lamp 314 is extinguished and lamp 316 is illuminated indicating the minimum outbound preference interval is being timed. The combination of relays OGL and GY energized and relay IGL deenergized provides a red signal over the reversible lane for inbound traffic and a green signal for outbound traffic.

The positions 9 and 22 of the banks LA are timed by multiplying the time of the RC time constant of the capacitor 260 and adjustable resistance 256 through position 9 of bank LA1, as previously described, and the wipers of both groups of banks advance together from position 26 to position 1 of bank LB, previously described.

Positions 10 and 23 of the banks LA are rest positions in outbound preference and so long as the relays OR and IR remain energized and deenergized respectively the lane changing unit may remain at rest in outbound preference. In position 10 of bank LA4 indicator lamp 316 is extinguished and lamp 319, the outbound preference rest indicator lamp, is illuminated.

When traffic conditions return to a more balanced condition and relay IR is again energized, a charging circuit from the D.C. supply through resistance 269, contact 320 of relay IR, lead 321, lead 322 to position 10 of bank LA1 through to the capacitor 260 is provided and the motor magnet MM1 is energized and causes advance of the wipers of the banks LA to positions 11 and 24. In position 11 of the bank LA4 the indicator lamp 323, the clearance for outbound preference indicator, is illuminated and lamp 319 is extinguished.

Positions 11 and 24 of banks LA are the clearance from outbound preference interval positions and the capacitor 260 is charged from the D.C. supply through part of the potential divider PD+, adjustable resistance 259, position of bank LA1, lead 273, lead 274 to capacitor 260. Upon closure of contacts 275 and 276 motor magnet MM2 becomes energized while motor magnet MM1 remains deenergized. The wipers of line switch banks LB are advanced, step-by-step 25 times to position 26 where a ground connection is provided for motor magnet MM1 through bank LB2 and the capacitor 260 is rapidly charged through position 26 of bank LB1 and resistance 292. Both motor magnets MM1 and MM2 are energized and deenergized,

as previously described, and the wipers of banks LA are advanced to positions 12 and 25 while the wiper of banks LB are advanced off position 26 to position 1.

During the clearance from outbound interval a red signal is maintained over the reversible lane to inbound traffic and a steady yellow or clearance signal is displayed over the reversible lane to outbound traffic as by energization of relay OGL and deenergization of relays IGL and GY.

Position 12 of bank LA1, the normal minimum interval is similar to position 6 of bank LA1 and provides a charging circuit from the D.C. through part of the potential divider PD+, adjustable resistance 253, lead 308, contact 327 of relay AIR, lead 324 to position 12 and through to the capacitor 260 as previously described. The interval is timed similar to that described with reference to position 6 and the signals displayed, including the indicator lamp illuminated, are all similar to the signals displayed and indicator lamp illuminated in position 6 previously described.

The position 12, the normal minimum interval, terminates as the wipers of banks LA are advanced to positions 13 and 26 and the wipers of the banks LB are advanced from position 26 to position 1.

Position 13 of bank LA1 is a skip position, the capacitor 260 being charged rapidly from the D.C. supply through resistance 269, lead 325, lead 326, position 13 of bank LA1 through to capacitor 260.

The wipers of the banks LA are advanced from positions 13 and 26 to positions 1 and 14 while the wipers of banks LB remain on position 1.

Thus the lane changing unit of FIG. 10 has been sequentially stepped through a complete cycle from its normal rest position, positions 1 and 14 of banks LA and position 1 of banks LB through thirteen steps of the banks LA back to positions 1 and 14 and also through the multiplying steps of the banks LB.

During the cycling operation of the lane changing unit, the three output relays IGL, OGL and GY of FIG. 10 have been energized and deenergized in combination to provide outputs via leads MIG, MOG and MCL to a signal control circuit such as illustrated in FIG. 3 for example, which signal control circuit or local lane changer provides illumination of the signal lamps, all as described above.

It should be understood that additional signal control circuits or local lane changers may be added to the lane changing system by connecting the additional local lane changers in parallel with the local lane changer assumed connected in the lane changing system herein.

It should be further understood that the line switch banks LB1, LB2, LB3 and LB4 are employed as a time multiplying mechanism and although 26 positions are illustrated the number of positions may be modified as desired so as to provide a larger or smaller multiplying factor. The multiplying factor may be reduced by reducing the number of positions in the banks LB, in particular by eliminating any or all of the positions 2 through 25 of the banks LB1, LB2, LB3 and LB4. The multiplying factor may be increased by increasing the number of positions between the positions 2 and 25, to duplicate a typical position, position 3 for example.

It may be desired to eliminate multiplication of the timing interval. This may be accomplished by removal of the lead 282 from the coil of the motor magnet MM2 so as to prevent operation of the motor magnet MM2 and, in addition thereto, by supplying a constant ground connection to the moving part of contact 275 by connecting lead 279 directly to ground. Under this arrangement the wipers of the banks LB will remain in position 1 and will be ineffective during normal operation of the lane changing unit.

The several positions 1 through 13 and 14 through 26 of the banks LA are allocated to certain parts of the complete cycle of the lane changing unit. In this respect

the positions 1 and 14 are allocated to the normal or balanced traffic rest condition; positions 2 and 15 to clearance to inbound peak traffic condition; positions 3 and 16 to minimum time for the inbound peak traffic condition; positions 4 and 17 to the inbound peak traffic rest condition; positions 5 and 18 to clearance from inbound peak traffic condition; positions 6 and 19 to the minimum time for the normal or balanced traffic condition; positions 7 and 20 to the normal or balanced traffic rest condition; positions 8 and 21 to clearance to outbound peak traffic condition; positions 9 and 22 to the minimum time for the outbound peak traffic condition; positions 10 and 23 to the outbound peak traffic rest condition; positions 11 and 24 to the clearance from the outbound peak traffic condition; positions 12 and 25 to the minimum time for the normal or balanced traffic condition; positions 13 and 26 a skip position to absorb an unused position in the cyclic switch.

It should be noted that certain positions of the line switch LA perform identical functions, as for example positions 1 and 14 and positions 7 and 20 are both normal or balanced traffic rest conditions. Such duplication of functions becomes necessary when one multiple position line switch is employed to provide separation of cyclic functions.

Skipping positions in certain conditions of operation of master lane changer of FIG. 10

Since these certain positions of the banks LA are allocated to parts of a complete cycle, provision is made to skip through certain of the allocated positions of the banks LA without normal response thereto, when, for example, the lane changing unit is at normal traffic rest, in positions 1 and 14 and traffic calls for outbound peak traffic conditions.

Circuitry is provided to temporarily convert the positions 2 through 6 inclusive and 15 through 19 inclusive, of the banks LA into skip positions while the wiper contacts of the banks LB are held in position 1, and to hold the output leads or output relays energized and deenergized as in positions 1 and 14 of banks LA temporarily during this skipping operation.

As described above, demand by the master controller, MC, for outbound peak traffic conditions is indicated by maintaining output lead OG energized and by deenergizing output lead IG thus cause relay OR of FIG. 10 to remain energized and cause relay IR to become deenergized.

Let it be assumed that the lane changing unit is in positions 1 and 14 of banks LA and position 1 of banks LB, thus in the normal or balanced traffic rest position and that subsequently the balance of traffic on the roadway RY alters so as to demand outbound peak traffic conditions. The lead IG would become deenergized thus dropping out relay IR while lead OG remains energized holding relay OR energized.

Deenergization of relay IR would open its contacts 353, 570 and 320 and close its contacts 329, 313 and 302. Closure of contact 329 completes a circuit to energize relay AOR from an A.C. supply through the coil of relay AOR, lead 330, contact 331 of relay OR, contact 329, lead 332, position 1 of bank LA2 to ground.

Energized relay AOR closes its contacts 333, 334, 335, 336, 339, 340, 341 and 342 and opens its contacts 285, 309 and 263. Closure of certain of these contacts temporarily converts some of the allocated inbound traffic positions of the banks LA into skip positions.

When the relay IR drops out and the relay OR remains energized, the relay AOR becomes energized as previously described and a circuit for charging capacitor 260 is provided via contacts 313 and 312, lead 272, position 1 of bank LA1, the wiper contact, lead 273, lead 274, to capacitor 260. The capacitor 260 is rapidly charged and the wipers of the banks LA are advanced into positions 2 and 15 as previously described.

Closure of contact 333 provides a ground connection in positions 15, 16, 18 and 19 of the banks LA2 to motor magnet MM1 when contact 275 is closed. During normal advance of the wipers of the banks LA these positions serve as ground connections for motor magnet MM2, as previously described. However, open contact 285 now opens the ground connections to motor magnet MM2 in these positions 15, 16, 18 and 19 so that the motor magnet MM1 may advance the wipers of the banks LA from positions 1 and 14 through to positions 7 and 20 without waiting for the operation of the motor magnet MM2 and the advance of the wiper contacts of the banks LB as previously described during normal operation.

Contact 339 shunts the slow, controlled charging circuit between the D.C. supply and position 2 of bank LA1 (including part of the potential divider PD+ and adjustable resistance 251) and applies the D.C. through resistance 269, lead 325, contact 339 to position 2 of bank LA1. Upon closure of contact 275 motor magnet MM1 becomes energized via contact 275, lead 279, lead 294, lead 297, contact 333, lead 286, lead 289, position 15 of bank LA2 to ground. The ground connection for motor magnet MM2 is open at contact 285 so that MM2 remains deenergized and the wipers of the banks LA are advanced to positions 3 and 16 upon the subsequent deenergization of MM1 while the wipers of the banks LB remain in position 1. Thus the positions 2 and 15 have, in effect, become a skip step.

Contact 336 shunts the resistance in the slow, controlled, charging circuit between the D.C. and position 3 of bank LA1 and provides a rapid charging circuit for the capacitor 260 via resistance 269, lead 325, contact 336 to position 3 of banks LA1, the motor magnet MM1 becomes energized, finding a ground connection at position 16 of bank LA2.

Contact 335 ensures that capacitor 260 will be rapidly charged via resistance 269 and lead 325 and position 4 of bank LA1 in the event that relay IR becomes energized and relay OR becomes deenergized during the skipping operation and prior to the advance of the wipers from position 4 to position 5. Also, in position 4 of bank LA1, with relay OR energized and relay IR deenergized two additional charging circuits are provided to supply D.C. via resistance 269 through contact 302 and lead 305 to position 4 and through contact 303, lead 304 and lead 305 to position 4. The charging circuit via contact 302 and lead 305 ensures rapid charging of capacitor 260 in the event that relay IR remains deenergized during the skipping operation whether or not relay OR remains energized or becomes deenergized. The charging circuit via contact 303, lead 304 and lead 305 ensures rapid charging of capacitor 260 in the event that relay OR remains energized whether or not relay IR remains deenergized or becomes energized. Thus three parallel circuits to charge capacitor 260 are provided in position 4 to ensure that the skip advance of the wipers of the banks LA from positions 4 and 17 to positions 5 and 18 is accomplished.

Contact 342 shunts the slow, controlled charging circuit between the D.C. supply and position 5 of bank LA1 via resistance 269, lead 325, contact 342 to position 5. The motor magnet MM1 is energized having found a ground connection in position 18 of bank LA2. Thus the advance of the wipers of the banks LA to positions 6 and 19 is accomplished.

In position 6 contact 334 provides a rapid charging circuit for the capacitor 260 which replaces the slow controlled charging circuit previously described relative to position 6. The D.C. is supplied via resistance 269, lead 325, contact 334, lead 310 to position 6 of bank LA1. The advance of the wipers of the banks LA to positions 7 and 20 is made as previously described.

The relay AOR having been energized in position 1 as previously described closed its contact 340 which provides a holding circuit to ground via positions 2, 3, 4, 5

and 6 of bank LA2. In position 7 the ground connection for the relay AOR is broken and relay AOR becomes deenergized.

With the energization of the relay AOR in position 1 prior to the skipping operation, the contact 263 was opened by such energization and caused indicator lamp 262 to be extinguished and also held all the indicator lamps extinguished during the skipping operation. Also contact 341 was closed to cross connect relay IGL and OGL so as to hold both relays energized. With both relays IGL and OGL energized the contacts 315 and 299 are both held open so as to prevent relay GY from becoming energized. The combination of output relays IGL and OGL both energized and relay GY deenergized maintains the desired output from the lane changing unit so that the desired signal display to traffic may be maintained during the skipping operation, that is a signal display similar to that provided in position 1 of bank LA.

In position 7 the relay AOR becomes deenergized and its contacts return to their normal condition. The temporary skip condition of positions 2 through 6 inclusive and 15 through 19 inclusive is abated. The indicator lamp 262 that had been illuminated in position 1 and extinguished during the skipping operation is re-illuminated in position 7 and the cross connection between the relays IGL and OGL is broken.

In position 7 the capacitor 260 is rapidly charged from the D.C. supply through resistance 269, contact 313, contact 312, lead 272 to position 7 and the motor magnet MM1 is energized as previously described finding a ground connection via contact 275, lead 279, to position 20 of bank LA2. The advance of the wipers of the banks LA to positions 8 and 21 is made as previously described.

Thus the advance out of position 1 is accomplished and the temporary conversion into skip steps of positions 2, 3, 5 and 6 has been made thereby rapidly advancing the wipers of the banks LA from normal traffic rest, position 1, to position 2 and via skipping operation from position 2 through to position 7 and from position 7 to position 8 while the wipers of the banks LB remain in position 1.

It should be noted that if during the above described skipping operation the traffic flows on the road way RY should return to normal and the lead IG should become energized so as to set up a demand for balanced traffic conditions thus energizing the relay IR before the wipers of banks LA arrive in position 7 the lane changing unit will arrive at position 7, the balanced traffic rest position, and remain in position 7 because of open contact 313 of then energized relay IR in the charging circuit of position 7 between the D.C. supply and the capacitor 260.

With the wipers of the banks LA in positions 8 and 21, the clearance to outbound peak traffic interval is timed as previously described and the lane changing unit then advances its wipers to positions 9 and 22. Positions 9 and 22, the minimum time of outbound peak traffic condition, is also timed as previously described and the wipers are advanced to positions 10 and 23.

With the wipers of the banks LA in position 10 the lane changing unit may stop and remain at rest in the outbound peak traffic condition. So long as relay OR remains energized and relay IR remains deenergized the lane changing unit will remain at rest in positions 10 and 23.

Relay AIR is provided so that the lane changing unit may skip certain of the outbound allocated positions of the banks LA if the wipers of the banks LA should be at normal traffic rest in positions 7 and 20 and the balance of traffic alters so as to call for inbound peak traffic conditions. The contacts controlled by relay AIR perform the same function relative to the outbound traffic allocated positions of the banks LA as the contacts controlled by relay AOR perform relative to the inbound traffic allocated positions of the banks LA.

Let it now be assumed that the lane changing unit is at rest in positions 7 and 20 of the banks LA with relays IR and OR both energized and traffic alters so as to demand inbound peak traffic conditions. The input 5 lead IG would remain energized thus holding relay IR energized and input lead OG would become deenergized thus dropping out relay OR. When relay OR drops out and relay IR remains energized in position 7 the relay AIR becomes energized via a circuit from the A.C. 10 through the coil of relay AIR, lead 355, contact 353 of relay IR, contact 354 of relay OR, lead 356, position 7 of bank LA2 to ground.

Energized relay AIR closes its contacts 343, 344, 345, 346, 349, 350, 351 and 352 and opens its contacts 284, 15 327 and 264. Closure of certain of these contacts temporarily converts some of the allocated outbound traffic 20 positions of the banks LA into skip positions.

With the lane changing unit in positions 7 and 20 and relay OR becoming deenergized while relay IR remains 25 energized the previously described charging circuit via resistance 269, contact 270, contact 271 and lead 272 to position 7 of bank LA1 is completed to charge capacitor 260 as previously described.

The motor magnet MM1 is energized and deenergized 25 as previously described and the wipers of the banks LA are advanced to positions 8 and 21.

Closure of contact 349 shunts the slow, controlled 30 charging circuit between the D.C. supply and position 8 of the bank LA1 and provides a rapid charge circuit via resistance 269, lead 325, contact 349 and position 8 of bank LA1 to the capacitor 260. Upon closure of contact 275 motor magnet MM1 becomes energized via contact 275, lead 279, lead 294, lead 297, contact 343, contact 285, lead 286, lead 289, position 21 of bank LA2 to 35 ground. The ground connection for motor magnet MM2 is open at contact 284 so that MM2 is not now energized and the wipers of the banks LA are advanced to positions 9 and 22 via action of MM1 while the wipers of the banks LB remain in position 1 due to the inactive condition of MM2.

Closure of contact 343 provides a ground connection 40 in positions 21, 22, 24, and 25 of the banks LA2 to motor magnet MM1 when contact 275 is closed. During normal advance of the wipers of the banks LA these positions serve as ground connections for motor magnet MM2, as 45 previously described. However, open contact 284 now opens the ground connection to motor magnet MM2 in these positions 21, 22, 24 and 25 so that the motor magnet MM1 may advance the wipers of the banks LA from positions 7 and 20 through to positions 13 and 26 50 without waiting for the operation of the motor magnet MM2 and the advance of the wiper contacts of the banks LB as previously described, during normal operation.

Contact 346 shunts the slow controlled changing circuit 55 between the D.C. supply and position 9 of the bank LA1 and provides a rapid charging circuit for the capacitor 260 via resistance 269, lead 325, contact 346 to position 9 of bank LA1. The motor magnet MM1 becomes energized finding a ground connection at position 22 of bank LA2.

Contact 345 ensures that the capacitor 260 will be 60 rapidly charged via resistance 269, lead 325, contact 345, lead 322 to position 10 of bank LA1 in the event that the relay OR becomes energized and relay IR becomes deenergized during the skipping operation and prior to the 65 advance of the wipers from position 10 to position 11. Also in position 10 of bank LA1, with relay IR energized and relay OR deenergized two additional charging circuits are provided to supply D.C. via resistance 269 through contact 320, lead 321 and lead 322 and via contact 363 to lead 322 to position 10 of bank LA1.

The charging circuit via contact 363, lead 322 ensures 70 rapid charging of the capacitor 260 in the event that the relay OR remains deenergized whether or not relay IR remains energized or becomes deenergized and the charging circuit via contact 320, lead 321 and lead 322 ensures

rapid charging of capacitor 260 in the event that relay IR remains energized whether or not relay OR remains deenergized or becomes energized. Thus three parallel circuits to charge capacitor 260 through position 10 are provided to insure that the skip advance of the wipers of the banks LA from positions 10 and 23 to positions 11 and 24 is accomplished.

Energization and subsequent deenergization of MM1 advances the wipers of the banks LA to positions 11 and 24.

In positions 11 and 24 closed contact 352 shunts the slow controlled charging circuit between the D.C. supply and position 11 of bank LA1 and provides a rapid charging circuit for capacitor 260 via resistance 269, lead 325, contact 352 to position 11 of bank LA1.

Motor magnet MM1 is energized and finds a ground through position 24 of bank LA2. The advance of the wipers of the banks LA to positions 12 and 25 is as previously described.

Contact 344 replaces the slow controlled charging circuit between the D.C. supply and position 12 of bank LA1 with the rapid charging circuit including resistance 269, lead 325, contact 344, lead 324 to position 12 of bank LA1. Motor magnet MM1 is energized and finds a ground through position 25 of the bank LA2 and advances the wipers of the banks LA to positions 13 and 26 as previously described.

When the relay AIR became energized in position 7 contact 350 was closed to provide a holding circuit. Closure of contact 350 provided a ground connection in positions 8, 9, 10, 11 and 12 of bank LA2 to insure completion of the skipping operation once it has begun. With the advance of the wipers of the banks LA into positions 13 and 26 the relay AIR becomes deenergized and the positions 8 through 12 and 21 through 25 are returned to their normal conditions and are no longer skip positions.

With the energization of relay AIR in position 7 prior to the skipping operation, the contact 264 was opened by such energization and caused indicator lamp 262 to be extinguished and also held all the indicator lamps extinguished during the skipping operation. Also contact 351 was closed to cross connect relays IGL and OGL so as to hold both relays energized. With both relays IGL and OGL energized the contacts 315 and 299 are both held open so as to prevent relay GY from becoming energized. The combination of output relays IGL and OGL both energized and relay GY deenergized maintains the desired output from the lane changing unit so that the desired signal display to traffic may be maintained during the skipping operations, that is, a signal display similar to that provided in position 7 of bank LA.

With deenergization of relay AIR the cross connection between the relays IGL and OGL is opened and the illuminating circuit for the indicator lamps is closed resulting in the re-illumination of lamp 262 in position 13.

The position 13 and 26, as previously explained, are normal skip positions and the wipers of the banks LA are rapidly advanced to positions 1 and 14, the normal traffic rest position.

In positions 1 and 14 a rapid charging circuit for capacitor 260 is completed from the D.C. supply through resistance 269, contact 270, contact 271, lead 272 to position 1 of the bank LA1 as previously described.

It should be noted that if during the skipping operation the demand from the master controller MC was altered due to a change in traffic so as to cause relay OR to become energized before the wipers of banks LA are in position 1, contact 271 would open and the wipers of the banks LA of the lane changing unit would stop in positions 1 and 14, the normal traffic rest position.

However, with the relay OR deenergized and the relay IR energized the capacitor 260 is charged as previously described and the motor magnet MM1 is energized and deenergized to advance the wipers of the banks LA1 to positions 2 and 15.

The lane changing unit will now continue to advance through the positions 2 and 3 to position 4, the inbound peak traffic rest position, as previously described and will stop and rest in positions 4 and 17 so long as the master controller MC maintains the call for inbound peak traffic conditions.

Thus normal operation of the lane changing unit has been described and the skip operation of the lane changing unit has been described with the energization and de-energization, in combination of the output relays IGL, OGL and GY to provide the desired output to the local lane changer or signal control circuit thus providing the desired signal sequence for control of the direction of traffic flow on a reversible lane or lanes on a multi-lane 10 road way serving bi-directional vehicle traffic.

In the description above it was explained that the timing of an interval or position on a cyclic switch may be accomplished by slow controlled charging of a capacitor and that such slow controlled charging may be repeated, 20 as desired, to multiply the charging time of the capacitor so as to arrive at a desired time interval. The method of multiplication of time illustrated herein employed a group of four banks of line switches LB each bank having 26 positions. To insure that the wipers of the line switch 25 banks LB return to position 1 in the event that the wipers of the banks LA advance during the multiplying action and prior to the arrival of the wipers of the banks LB in the position 26, a self-interrupting energizing circuit is provided for motor magnet MM2 including lead 282, contact 291, lead 364, the positions 2 through 26 inclusive 30 of bank LB3, lead 365 and positions 14, 17, 20 and 23 of bank LA4.

OTHER ALTERNATE FEATURES

35 It may be desired to develop pseudo peak traffic conditions in the lane changing unit illustrated in FIG. 10 during balanced traffic conditions. This may be accomplished by the use of selector switches in the input leads IG and OG, the switches, similar to the switch 200 and 210 in FIG. 2, for selection between alternate input circuits to the coil of relays IR and OR of FIG. 10 similar to the alternate input circuits illustrated and associated with the relays IR and OR of FIG. 2.

A switch, such as switch 200 in FIG. 2, may be inserted 45 in the input lead OG in FIG. 10 for selection between a circuit directly connecting the input lead OG through the switch 200 to the coil of relay OR and a second circuit which includes a "break" contact, 204, for example of relay IR between the second position of the switch 200 and the coil of the relay OR so that when both leads IG and OG are energized the contact 204 in the second circuit between the second position of the switch 200 and the coil of relay OR would be opened by the energized relay IR to prevent relay OR from becoming energized.

55 With the switch 200 in the latter position, a call for balanced traffic conditions, as by energization of both input leads IG and OG by the master controller would produce the development of inbound peak traffic conditions by the lane changing unit since only relay IR would be energized and thus pseudo-inbound traffic conditions would be developed.

Of course a call for inbound peak traffic conditions, as by energization of input lead IG alone, would produce the development of inbound peak traffic conditions by the lane changing unit while a call for outbound peak traffic conditions, as by energization of input lead OG alone, would produce the development of outbound peak traffic conditions by the lane changing unit.

70 Obviously pseudo-outbound peak traffic conditions may be developed by the inclusion of a switch, such as switch 210 in FIG. 2, that may be inserted into the input lead IG in FIG. 10 for selection between a circuit directly connecting the input lead IG through the switch 210 to the coil of relay IR and a second circuit which includes a 75 "break" contact, 214, for example, of relay OR between

the second position of the switch 210 and the coil of the relay IR so that when both leads IG and OG are energized the contact 214 in the second circuit, between the second position of the switch 210 and the coil of relay IR would be opened by the energized relay OR to prevent relay IR from becoming energized.

In some lane changing systems in which a lane changing unit as illustrated in FIG. 10 is employed, it may be desired to eliminate some of the intervals illustrated in the lane changing unit in FIG. 10, as for example, it may be desired to eliminate the interval during which a clearance interval after a peak period is timed, such as positions 5 and 18 of the banks LA, the clearance from the inbound peak traffic condition and positions 11 and 24 of banks LA, the clearance from the outbound peak traffic condition, for example. Such intervals may be eliminated by substantially reducing the resistance in the charging circuits associated with the respective intervals. This would have the effect of rapidly stepping the wipers of the line switch banks LB through the multiplying positions so that the wipers of the banks LA in effect become rapidly advanced through the positions out of heretofore described timed intervals, during normal operation of the lane changing unit.

An alternate method of eliminating one or more intervals would be to make a skip-step, similar to the skip-step positions 13 and 26, out of the positions timing the interval to be eliminated. If, for example, positions 5 and 18 of the banks LA were to be converted into a skip-step the position 18 of bank LA2 would be connected to the ground lead for the motor magnet MM1 by the connecting the position 18 to the upper lead across the bank LA2, which is connected to lead 279 and disconnecting the position 18 from the lower lead across the bank LA2, which is connected to lead 289. Also the adjustable resistor 254 would be disconnected from position 5 of bank LA1 and position 5 would be connected to lead 325 to provide rapid changing of the capacitor 260. This modification would eliminate the operation of motor magnet MM2 and provide for rapid advance of the wipers of the banks LA from positions 5 and 18 to positions 6 and 19 while the wipers of the banks LB remain in position 1.

It should be noted that while a specific signal sequence is illustrated and described herein, it will be obvious to those skilled in the art that by suitable modification to the connections between the output relays IGL, OGL and GY and the line switch bank LA3, it is possible to produce any desired combination of output lines MIG, MOG and MCL energized during any specific interval.

This, together with suitable circuitry in the local lane changer, can be used to provide any required signal or sign display to traffic in the controlled lane or lanes.

By addition of more output relays, similar to IGL, OGL and GY and the addition of more banks of line switches to the banks LA, if required, further variations of signal display may be obtained.

The present invention has been presented with several variations and means for employing various modifications of the several units of the apparatus but it should be understood that additional modifications, variations and interchange of various units of the apparatus including substitution and rearrangement of the parts or elements may be made without departing from the spirit of this invention as described in the appended claims.

I claim:

1. A system for controlling and reversing the direction of traffic flow along two adjacent inner traffic lanes located between outer traffic lanes allocated to opposite directions respectively along a roadway, means for measuring traffic along all of said lanes in the respective opposite directions along said roadway, indicating means individual to each lane of said roadway for indicating permission and prohibition and clearance to the potential traffic directions thereon, comparison means for producing controlled output signals indicative of

traffic movement in one direction exceeding a pre-established relationship relative to traffic movement in the other direction, means for controlling said indicating means in response to said controlled output signals from 5 the comparison means resulting from said traffic measuring means for permitting traffic in one direction and prohibiting traffic in the opposite direction in said two adjacent traffic lanes respectively in response to measurement of substantially greater traffic in said one direction than in said opposite direction in said roadway and means 10 for controlling said indicating means for reversing the direction of permitted and prohibited traffic in said two adjacent traffic lanes respectively in response to said comparison measurement of substantially greater traffic 15 in said opposite direction than in said one direction by said measuring means, means for controlling said indicating means in response to said traffic measuring and comparison means for permitting traffic in said one direction in one lane of said two adjacent traffic lanes and 20 prohibiting traffic in said opposite direction in said one lane and permitting traffic in said opposite direction in the other lane of said two adjacent traffic lanes and prohibiting traffic in said one direction in said other lane in response to measurement of substantially equal traffic 25 in the respective directions and means for limiting the control of an initial change from like conditions on the adjacent inner lanes to a change affecting only the inner lane moving oppositely to its adjacent outer lane.

2. A system as in claim 1 and in which said means 30 for controlling said indicating means in response to said traffic measuring means includes means for providing a clearance indication to traffic in one direction and a prohibition indication to traffic in the opposite direction for a time period followed by providing prohibition indications in both directions for a further time period in 35 the lane being reversed in transition from permission in one direction alone to permission in opposite direction alone.

3. A traffic control system for control of the direction of traffic flow in at least two adjacent interior traffic lanes between outer lanes allocated to opposite directions of traffic, vehicle detection means individual to each direction of traffic for measuring the individual traffic flow, 40 comparison means for comparing at least two of said measurements, control means individual to each lane of said two adjacent interior traffic lanes for providing prohibition, permission and clearance of vehicle traffic in the respective directions of said two adjacent interior lanes, each said control means including a first relay and 45 a second relay, said comparison means providing a first output representing substantially greater traffic in one direction than the other direction and a second output representing substantial greater traffic in the said other direction than in said one direction and a third output 50 representing a combination of said first and said second outputs for substantially balanced traffic in the respective directions, first and second relay means, coupling means to supply said first output to said first relay in one said control means and a second coupling means to supply 55 said second output to said second relay in the other said control means, means in said one control means for connection to said first relay in said other control means and said second output connected to coupling means in said other control means for connection to said 60 second relay in said one control means, further means interlocking the first and second relays of the individual said control means to prevent concurrent operation of both said relays of the same control means but to permit opposite such relays to be operated in the two respective 65 control means upon a combination of said first and second outputs, further means individual to each said respective control means and controlled by said relays for so indicating to traffic in both directions along each 70 of the respective said two adjacent lanes permission, prohibition or clearance to provide permission to traffic

75

in said one direction and prohibition to traffic in the said other direction in both said two adjacent lanes in response to said first output and, means to provide permission to traffic in said other direction and prohibition to traffic in said one direction in both said two adjacent lanes in response to said second output and means to provide permission to traffic in said one direction and prohibition to traffic in said other direction in one lane of said two adjacent lanes and permission to traffic in said other direction and prohibition to traffic in said one direction in the other lane of said two adjacent lanes in response to said combination of said first and said second outputs.

4. In a traffic control system having two or more interior traffic lanes between two or more outer lanes which outer lanes are allocated to traffic in opposite directions respectively, a system for reversing the direction of traffic in the interior lanes automatically in response to directional traffic volume comprising, means included in each of said interior lanes for controlling signal indications in each respective said interior lanes, interlocked means for producing a first control of each interior lane to preset the direction of permissible traffic movement for opposite directions to a direction corresponding to that of the nearest outer lane, means to prevent any one interior lane from being reversed in direction with respect to both adjacent lanes on both sides of said one interior lane, and means for responding to unequal traffic volumes in the two directions to provide operation of one of said signal indication control means to provide signal indications for each of said two interior lanes directing traffic to flow in the same direction in both said interior lanes in accordance with the direction of greater traffic volume.

5. A traffic control system for controlling and reversing the flow of traffic in one or more traffic lanes between other traffic lanes allocated to traffic in opposite directions respectively along a roadway including traffic measuring means individual to each direction of said traffic flow in the several lanes, means for comparing the traffic measured by said two traffic measuring means, means for indicating selectively directional permission or prohibition or clearance or caution for said one or more traffic lanes, control means responsive to said comparing means for controlling said indicating means, cyclic switching means for providing an operating cycle for said indicating means controlled by said comparison means and including two successive positions each for providing permission for one direction of traffic and prohibition in the opposite direction of traffic in said one or more reversible lanes in response to said comparison means indicating substantially greater traffic in said one direction, timing means coupled with said cyclic switch in one of said successive positions for providing a minimum time period and means coupled with said cyclic switch in the other of said successive positions for providing a rest period dependent on a change in relative traffic indication by said comparison means, said cycle having a following position providing a time period for clearance to the traffic direction last having said permission indication while maintaining prohibition in the opposite direction, followed by two successive positions for providing caution indications in both directions and providing a minimum time period and a rest period respectively, said rest period being dependent on continued substantially equal traffic indication for the two directions by the comparison means, said cyclic switching means advancing therefrom in response to substantially unequal traffic indication by said comparison means, said cycle having a following position providing a caution indication in the traffic direction next to receive a permission indication and providing a prohibition indication in the other direction, and then continuing to its

next permission-prohibition indication positions, and said cycle having a further series of positions complementary to the aforesaid series for providing corresponding but reversed indications for the opposite direction in response to said comparison means indicating greater traffic in the opposite direction.

5 6. A traffic control system as in claim 5 and including means controlled by said comparison means and said cyclic switch means for skipping from the caution rest position rapidly through the intervening positions of 10 the cycle to the caution indication position preceding the permission position while maintaining caution indications in both directions in response to a change of indication of said comparison means from substantially equal 15 traffic to greater traffic in the direction opposite to that which would normally be given permission indication in said intervening positions.

7. A traffic control system as in claim 6 and including means for interrupting said rapid skipping operation in the intervening caution rest position in response to a change of traffic demand from unequal demand to substantially equal demand as indicated by said comparison means during such skipping operation.

8. A traffic control system for reversing traffic in 25 two or more interior traffic lanes between two or more outer lanes in which said outer lanes are allocated to traffic in opposite directions respectively, including mutually interlocking means individual to each of said interior lanes, signaling means, the respective said interlocking and signaling means normally being oppositely preset to provide signals permitting traffic to flow in said interior lanes only in the same direction as their adjacent outer lanes in response to substantially balanced 30 traffic demand in said opposite directions, means for measuring traffic flow in the respective lanes for determining the relative demand in each direction, means for providing a directional output indicative of substantially greater traffic flow in said lanes in one direction than in the other direction, said output being connected to each said interlocking and signaling means for operating one of said signaling means to reverse its signals to permit traffic flow in said one direction only in its associated lane, while maintaining the other signaling means in its said normal signal condition so that the signals in the interior lanes then permit traffic to flow in the same one direction in response to increased traffic demand in a said one direction.

9. A traffic lane changer responsive to directional traffic demand comprising a cyclic timing means including a plurality of stepping contacts and associated control circuits providing timed advance of the cyclic means, directional traffic measuring means for determining the rate of traffic flow in respective directions and for providing an output indicative of equal and unequal traffic rates in respective directions, control means responsive to said equal and unequal outputs respectively for controlling said control circuits thereby controlling the 50 operation of said cyclic means, said control means controlling a stepping contact and its associated control circuit for equal measurements to provide a rest position for said cyclic means, and said control means controlling second and third stepping contacts and their associated 55 control circuits respectively in response to unequal rates in one or the other direction respectively to provide additional respective rest positions, for said cyclic means, such control of said circuits thereby stopping the advance 60 of said cyclic means in said rest positions but permitting advance from the rest position in response to a change from the one of said rate conditions which caused such rest condition, and means for bypassing certain of said controlled contacts to provide for rapid advance through 65 certain contact positions and circuit means controlled by 70

59

said cyclic means for operating traffic directing means
for controlling directional use of the said lane.
